UNITED STATES PATENT OFFICE

JOHN WICKS, OF OAK PARK, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

MULTIOFFICE TELEPHONE SYSTEM

Application filed May 29, 1931. Serial No. 540,992.

This invention relates to multi-office telephone systems in general, but is concerned more particularly with such systems including both automatic and manual exchanges 5 and employing alternating current control over the inter-office trunk lines.

The invention has for its broad object the provision of new and improved circuits for effecting the control of inter-office connections by means of alternating current impulses transmitted over two-way trunk lines.

According to one feature of the invention, alternating current impulses of different lengths are transmitted over the trunk lines 15 and converted into the proper direct current signals at the respective ends of the trunk line to effect the operation of the switches and supervisory signals.

Another feature of the invention lies in 20 the novel toll offering arrangement which includes a new and improved toll-offering connector switch and corresponding improvements in the manual switchboard circuits.

The above and other features of the invention will be more clearly understood from 25 a perusal of the following specification when read in connection with the accompanying drawings, comprising Figs. 1 to 6, inclusive, which show by means of the usual schematic 30 diagram sufficient portions of a multi-office telephone system to enable the present invention to be understood.

Fig. 1 is a trunking layout of the telephone 35 system including a manual exchange and two automatic exchanges, A and B. The manual exchange is indicated at the left of the drawings and comprises an operator's position circuit PC, an operator's cord circuit CC, and a trunk circuit TC which forms the manual 40 end of two-way trunks extending to the first automatic exchange A. Automatic exchanges A and B are three-digit exchanges including selectors and connectors. The two-way trunks from the manual exchange terminate at exchange A in repeaters, such as R1, and incoming selectors, such as IS1. These trunks are accessible to selectors from 45 the 0 level. Automatic exchanges A and B are interconnected by two-way trunk lines terminating at exchange A in repeaters, such

as R2, and incoming selectors, such as IS2, and at exchange B in repeaters, such as R3, and incoming selectors, such as IS3. Repeaters R2 and R3 are identical to the repeater R1 terminating the trunk from the 55 manual exchange. The trunks extending to exchange B are accessible over the ninth level of the selectors in exchange A. The trunks extending to exchange A are accessible over the 0 level of the selectors in exchange B. 60

Fig. 2 discloses a cord circuit CC, which is one of a number of similar circuits of an operator's position, and an operator's position circuit PC and an operator's telephone circuit OTC which are common to the cord 65 circuits at the position.

Fig. 3 discloses the trunk circuit TC which is accessible at the manual board over jack J and terminates the two-way trunk line extending to automatic exchange A and comprising conductors 1 and 2. 70

Fig. 4, comprising parts A and B, discloses the two-way repeater circuit R1 located in the automatic exchange A, and terminating 75 the two-way trunk line comprising conductors 1 and 2, connecting exchange A to the manual exchange.

Fig. 5 discloses an incoming selector circuit IS1, a local selector S1, and a subscriber's substation T1 and the associated lineswitch LS1 having access to local selectors, such as S1. The banks of selectors IS1 and S1 are multiplied and have access to the trunks extending to the manual exchange 80 over the 0 level by way of a repeater, such as R1, over conductors 24, 26, and 28. The incoming selector IS1 is controlled by repeater R1 over conductors 25 and 27. 85

Fig. 6 discloses a connector circuit C1 90 which is accessible to local selectors, such as S1, and incoming selectors, such as IS1, and in turn has access to the subscribers' substations, such as T1 and T3, in automatic exchange A. A repeater R2 indicated at the top of the figure is accessible from the ninth level of the local and incoming selectors and terminates a two-way trunk line, comprising conductors 658 and 659, extending to automatic exchange B. Repeater R2 is in all re- 95 100

spects identical to repeater R1 which is shown in detail in Fig. 4.

Referring now to the trunking layout shown in Fig. 1 of the drawings, a brief description will first be given of the manner in which the various connections are set up in the multi-office system shown. Assuming first that the operator at the manual exchange has received a request for a connection with the subscriber at substation T3 in automatic exchange A. The operator inserts the calling end of the cord circuit CC into the jack J, associated with a trunk extending to exchange A. When the plug of the cord is inserted in the jack, the trunk circuit TC operates to send a preliminary seizing impulse of alternating current over the trunk line. This impulse of alternating current is received by the repeater R1 in exchange A and prepares the repeater for operation on an incoming call. The loop circuit to the incoming selector IS1 is also completed responsive to the preliminary impulse. The operator now proceeds to dial the telephone number of substation T3, which it will be assumed is 323. Responsive to the operation of the dial, the trunk circuit TC transmits corresponding impulses of alternating current over the trunk line which are received by the repeater R1, and are converted into direct current impulses to operate the incoming selector switch IS1 and the connector switch C1. In case the called line is idle the connector C1 rings automatically and, when the called subscriber at substation T3 answers, reverses battery back to the repeater R1. Responsive to the reversal of current, repeater R1 transmits an alternating current impulse over the trunk line to trunk circuit TC to give answering supervision. Trunk circuit TC brings about the extinguishing of the supervisory lamp at the operator's position to inform the operator that the called party has answered.

At the end of the conversation when the called subscriber hangs up his receiver the battery connections at connector C1 are again restored to normal. This causes the repeater R1 to transmit a disconnect impulse of alternating current over the trunk line, which causes the trunk circuit TC in the manual exchange to again light the supervisory lamp to show that the called subscriber has disconnected. When the operator removes the cord CC from jack J, the trunk circuit TC transmits a long impulse of alternating current over the trunk line. This long impulse of alternating current is received by repeater R1 and brings about the release of the incoming selector switch IS1 and the connector switch C1 and also restores repeater R1 to normal. The apparatus has now completely restored to normal.

Assuming now that a subscriber, such as the subscriber at substation T1, in the automatic exchange A wishes to talk to a sub-

scriber who can be reached only through the manual exchange. When the subscriber at substation T1 lifts his receiver, lineswitch LS1 is operated and searches for an idle trunk, such as that extending to the local selector S1. The calling subscriber then dials the digit 0, whereupon selector S1 is operated to the tenth level and selects an idle trunk extending to the manual exchange, such as the one accessible by way of repeater R1. When repeater R1 is seized, it transmits a calling signal over the inter-office trunk line which is received by the trunk circuit TC, and causes the lighting of the calling lamp at the operator's position. On noting the lighted condition of the trunk lamp the operator inserts the answering plug of a cord circuit, such as CC, into the associated jack, thereby causing the trunk circuit TC to transmit an alternating current impulse over the trunk line to exchange A. Repeater R1 responds to this impulse and reverses the battery over the calling line to perform a metering function in case metered service is used. The operator then completes the desired connection over the other end of cord CC. At the end of the conversation, when the calling subscriber releases, repeater R1 transmits an alternating current impulse over the trunk line to light the supervisory lamp at the operator's position. When the operator removes the plug from the trunk jack, a release signal is transmitted over the trunk line to restore the equipment in the automatic exchange A to normal.

In case the manual operator receives a call for a subscriber, such as the subscriber at substation T2, in the automatic exchange B, she inserts the plug of a cord, such as CC, into the jack J, thereby causing the trunk circuit TC to transmit an alternating current impulse over the trunk line to prepare the switches in exchange A. Repeater R1 closes the loop to incoming selector IS1 in the manner previously described. To call subscriber substation T2, the manual operator dials the number 9332. Responsive to the operation of the dial in accordance with the first digit 9, the trunk circuit TC transmits alternating current impulses over the trunk line which are converted into direct current impulses by repeater R1 to operate the incoming selector switch IS1 to the ninth level. The switch automatically hunts in this level for an idle trunk extending to automatic exchange B by way of a repeater, such as R2. When repeater R2 is seized, it transmits a signalling impulse of alternating current over the trunk line which is received by repeater R3 and causes the repeater to close the loop to the incoming selector IS3. Responsive to the dialling of the remaining digits, trunk circuit TC transmits corresponding impulses of alternating current over the trunk line extending to exchange A, which are received

by the repeater R1 and converted into direct current impulses. The direct current impulses operate the repeater R2 which again converts the impulses into alternating current impulses for transmission over the trunk line extending to the automatic exchange B. These alternating current impulses are received by repeater R3 which converts them into direct current impulses for operating the incoming selector switch IS3 and the connector switch C3 to establish the connection to the subscriber at substation T2. Substation T2 is signalled automatically and when the subscriber answers, the reversal of battery in connector C3 causes repeater R3 to transmit an answering supervisory signal over the trunk line. This alternating current signal is received by repeater R2 which reverses the battery through the incoming selector to repeater R1. Responsive to the reversal of battery, repeater R1 transmits an answering supervisory signal over the trunk line to the manual exchange which is received by the trunk circuit TC. The trunk circuit in turn extinguishes the supervisory lamp at the operator's position to inform the operator that the called subscriber has answered.

At the end of the conversation, when the subscriber at substation T2 hangs up his receiver, the battery connections from the connector to repeater R3 are again reversed to normal and repeater R3 transmits a disconnect impulse of alternating current over the trunk line to the exchange A. Repeater R2 responds to this impulse and again reverses the battery connections to repeater R1 to normal. Repeater R1, responsive to the battery reversal, transmits a disconnect impulse of alternating current over the trunk line, which is received by trunk circuit TC and results in the lighting of the supervisory lamp to indicate to the operator that the called subscriber has hung up his receiver. When the operator pulls out the plug, a release impulse is transmitted over the trunk line by the trunk circuit TC. Responsive to this impulse, repeater R1 opens the loop extending through incoming selector IS1 to repeater R2, causing this repeater to send a release pulse over the trunk line to automatic exchange B. Repeater R3 responds to this impulse to open the loop extending to the automatic switches in the exchange and thereby releasing the switches and also restoring repeater R3 to normal. All the equipment which was used in this connection has now been restored to normal position.

Subscribers in exchange B can call subscribers in exchange A by dialling the digit 0 and then the regular telephone number of the wanted subscriber. The dialling of the digit 0 operates the local selector, such as S2, to seize a repeater, such as R3, connected to a trunk line extending to exchange A. The re-

peater R2 at the automatic exchange A terminates in an incoming selector, such as IS2, and this selector and a connector, such as C1 or C2, respond to the regular telephone number of the wanted subscriber to extend the desired connection. In case the subscriber at substation T2 in exchange B wishes to establish a connection which can be completed only by the manual operator, he dials the digit 0 thereby extending a connection to automatic exchange A and then dials a second digit 0 which operates the incoming selector IS2 to select an idle repeater, such as R1, terminating one of the trunk lines extending to the manual exchange. The repeaters R1, R2, and R3 operate in these connections in a similar manner as previously explained for the other connections.

Having described the trunking layout of the exchanges in general, and having described generally the various connections which can be established within the system, the operation of the circuits will now be explained in detail with reference to Figs. 2 to 6, inclusive. These figures should be laid out in order from left to right with Fig. 2 at the extreme left.

Call from manual exchange to substation T3 in exchange A

A call from the manual exchange to substation T3 in the automatic exchange A will first be described. It will be assumed that the operator has received a call over a trunk line which may be in all respects similar to the trunk line terminating in the trunk circuit TC and that she has answered the call by inserting the plug P1 of cord circuit CC into the calling jack and operating key K to its left-hand position to connect her telephone circuit with the calling line. The operation of key K to its left-hand position completes a circuit for relay 200 in the cord circuit extending from battery, lower winding of relay 200, spring 210 and its make contact, conductor 227, armature 233 and its resting contact to ground. Relay 200 operates and closes a locking circuit for itself extending from battery, upper winding of relay 200, armature 204 and its working contact, working contacts of key spring 209 and said spring, conductor 226, winding of relay 232 to ground. Relay 232 operates in this circuit in series with relay 200 and at armature 233 and its resting contact opens the initial energizing circuit of the latter relay. At armature 235 and its resting contact it opens the circuit of the monitoring relay 238. At armatures 236 and 234 and their respective working contacts it connects the operator's telephone circuit to the tip and ring of plug P1 to allow the operator to talk with the calling party. It will be assumed that the calling party desires to talk with the subscriber at substation T3

in exchange A. The operator thereupon inserts plug P of cord circuit CC into the jack J and proceeds to dial the desired number, which in this case is 323.

5 Responsive to the insertion of plug P into jack J, the relay 303 in the trunk circuit operates in series with relay 274 in the common position circuit PC over the following circuit: from ground, upper winding of relay 303, 10 resting contact of armature 315 and said armature, sleeve of jack J and plug P, working contact of armature 203 and said armature, conductor 221, armature 270 and its resting contact, upper and lower windings of relay 15 274, to battery. Relay 274 in operating, at armature 275 and its working contact completes a circuit for relay 278. Relay 278 operates and at armature 279 and its working contact completes a circuit for the supervisory lamp 215 extending from ground, 20 armature 275 and its working contact, working contact of armature 279 and said armature, conductor 225, key spring 208 and its working contact, supervisory lamp 215, to battery and in parallel therewith through resistance 217 to battery. In the trunk circuit TC, relay 303 operates and at armature 304 and its working contact, completes a circuit for relay 367 extending from ground, 25 armature 304 and its working contact, resting contact of armature 328 and said armature, winding of relay 367 to battery. Relay 367 operates, and at armatures 368 and 369 connects the source of alternating current to the outgoing trunk line comprising conductors 1 and 2.

The alternating current used for signaling is obtained through a special frequency doubling transformer disclosed in the lower 40 portion of Fig. 3. Leads 380 and 381 are connected to the commercial power source having a frequency of about 60 cycles. The frequency doubler consists of a transformer having a primary and a secondary winding 45 with the primary winding divided into two sections. Lead 381 is connected to the center point of the primary winding while the outer terminals of this winding are connected to two dry discs rectifiers 378 and 379, and the other lead 380 extending from the commercial power source is connected to the midpoint of these rectifiers. During one 50 half-cycle of the alternating current, the current will be in such a direction that it will flow through rectifier 379 and upward through the lower half of the primary winding and back over lead 381. During the other half-cycle of the current, current will flow over lead 381, upper section of the primary 55 winding, rectifier 378, and back over lead 380. Thus it is seen that the two opposite half cycles of alternating current flow through portions of the primary winding in the same direction, thereby producing magnetic flux 60 in the core of transformer 377 in accordance

with two half cycles which are in the same direction through the core. Each of these half-cycle changes in the magnetic flux will produce a complete cycle of alternating current in the secondary winding of the transformer. Thus the output current of transformer 377 will have a frequency which is twice that of the commercial power source. This output current is taken through lamps 70 375 and 376 and connected to the trunk line 75 at armatures 368 and 369, as previously explained.

Returning now to the point where relay 367 operated and connected the alternating current source to the trunk line, the relay 80 also completes a circuit for relay 322 at armature 370 and its working contact. This circuit extends from ground, spring contact 300 on jack J which is closed as soon as the plug P is inserted into the jack, armature 312 and 85 its resting contact, working contact of armature 370 and said armature, normally closed springs controlled by armature 327, winding of relay 322, to battery. The closure of jack 90 spring 300 also completes a circuit for relay 360. Relay 360 is equipped with a weighted spring armature 361 and an appreciable interval of time elapses before this armature comes to rest in engagement with its working contact. Relay 362 is made slow-to-operate 95 by a copper slug on the armature end of the core and will, therefore, not operate until its circuit remains permanently closed after armature spring 361 comes to rest in engagement with its working contact. When relay 100 362 operates, it completes a circuit for the busy visual 302 at armature 363 and its working contact, and at armature 364 and its working contact it closes a point in a second circuit for relay 367 extending from ground, 105 armature 329 and its resting contact, armature 341 and its resting contact, armature 364 and its working contact, winding of relay 367, to battery.

Relay 322 is made slow-to-operate by a copper slug on the armature end of its core and does not operate for a short time after its circuit is closed at armature 370 of relay 367. When relay 322 finally operates it completes a locking circuit for itself at armature 327 and its working contact, to ground at the jack springs 300. At armature 329 and its resting contact and armature 328 and its resting contact it opens the two circuits previously described for relay 367, allowing this relay to drop back and cut-off the alternating current from the trunk line thereby ending the preliminary pulse which was being transmitted over the trunk line extending to exchange A. At the double make contacts 323 and 325, relay 322 completes a circuit from grounded conductor 382, contacts 323 and 325, armature 334 and its resting contact, winding of relay 347, resistance 383 to battery. Relay 347 operates and at armature 120 125 130

- 352 and its working contact completes a second circuit for the busy visual 302, and at armature 349 and its resting contact it opens a point in the circuit of relay 353.
- 5 Referring now to the repeater R1 shown in Figs. 4A—4B of the drawings, the preliminary impulse of alternating current which was transmitted over conductors 1 and 2 by the trunk circuit TC in the manner just described, operates relay 435 by way of armatures 424 and 425 and their respective resting contacts and the left-hand windings of repeating coil 437. Relay 435 completes a circuit for relay 445 extending from ground, normally closed contacts controlled by armature 413 of relay 410, armature 436 and its working contact, conductor 11, normally closed springs controlled by armature 449, armature 469 and its resting contact, lower winding of relay 445, to battery. Relay 445 operates its armature 450, thereby preparing a locking circuit for itself over both of its windings but the upper winding is short-circuited over the above traced circuit 25 until relay 435 releases at the end of the preliminary impulse. When relay 435 releases and opens the ground connection to relay 445 at armature 436, relay 445 operates all of its armatures and locks operated in a circuit extending from ground, normally closed springs controlled by armature 413, conductor 12, armature 450 and its working contact, upper and lower windings of relay 445, to battery.
- 30 35 At armatures 446 and 457 and their respective working contacts relay 445 completes a loop circuit extending to the incoming selector IS1, Fig. 5, to prepare the selector for operation. This loop circuit extends from ground, lower winding of line relay 500 in selector IS1, resting contact of armature 514 and said armature, conductor 27, working contact of armature 457 and said armature, conductor 28, lower-right-hand winding of repeating coil 437, conductor 14, resting contact of armature 493 and said armature, lower winding of supervisory relay 471, working contact of armature 451 and said armature, conductor 13, upper-right-hand winding of repeating coil 437, conductor 3, armature 446 and its working contact, conductor 25, armature 511 and its resting contact, upper winding of line relay 500, to battery. Line relay 500 operates in 40 this circuit and at armature 501 and its working contact completes a circuit for release relay 502.
- 45 Relay 445 in operating, at armature 447 and its working contact connects ground to the release conductor 26 in order to busy the repeater R1 in the banks of local and incoming selectors, such as S1 and IS1. This ground is also connected to the upper winding of relay 471 energizing this winding, but 50 relay 471 does not operate since the current
- through its lower winding is in such a direction as to oppose the current through its upper winding. At armature 449 and its working contact a point is closed in the impulsing circuit extending to the impulse correcting relays 488, 494, and 499. The repeater R1 and the incoming selector switch IS1 are now in readiness to receive the digit impulses of the desired telephone station.
- 55 The foregoing operations have all occurred responsive to the insertion of the plug P of cord circuit CC into the trunk jack J. As soon as the operator turns the dial 282 from its normal position, preparatory to dialling the desired telephone number, a circuit is completed for relays 268 and 272 in series from ground at the dial off-normal springs, key spring 266 and its resting contact, winding of relay 272, winding of relay 268, to battery. Relays 268 and 272 operate in this circuit. At armature 269 and its resting contact, relay 268 opens the ring conductor extending to plug P1, and at armature 270 and its resting contact it opens the circuit of the supervisory relay 274 and sleeve relay 303 60 and at the working contact of this armature completes a point in the dialling circuit. At armature 273 and its working contact, relay 272 connects battery through resistance 283 to the ring conductor over working contact of armature 273 and said armature, conductor 223, armature 206 and its working contact, ring of plug P and jack J, lower-left-hand winding of repeating coil 318, winding of relay 314, upper winding of relay 310, resting contact of armature 304 and said armature, to ground. This circuit is completed as soon as relay 303 releases responsive to the opening of its circuit at armature 270 of relay 268. Relay 314 operates in this circuit but relay 310 is adjusted so that it will not operate in series with relay 314 and resistance 283. At armature 315 and its working contact, relay 314 connects the sleeve of jack J to ground at armature 311 and its resting contact. At armature 317 and its working contact it connects the tip of jack J to the winding of the impulse repeating relay 371. At armature 316 and its front contact it prepares a point in the energizing circuit of relay 367.
- 65 When relay 303 releases as previously described, a circuit is completed for relay 307 which operates without effect at this time. The impulsing circuit to relay 371 has now been completed from ground, armature 311 and its resting contact, working contact of armature 315 and said armature, sleeve of jack J and plug P, working contact of armature 203 and said armature, conductor 221, armature 270 and its working contact, resting contact of key spring 265 of the dial transfer key 263, impulsing springs of dial 282, key spring 280 and its resting contact, key spring 264 and its resting contact, work-

ing contact of armature 271 and said armature, conductor 220, armature 202 and its working contact, tip of plug P and jack J, armature 317 and its working contact, winding of relay 371 to battery. Relay 371 operates in the circuit and at armatures 372 and 373 and their respective resting contacts opens points in the outgoing trunk conductors 1 and 2. At armature 374 and its working contact it completes a circuit from ground, working contact of armature 374 and said armature, working contact of armature 316 and said armature, winding of relay 367, to battery. Relay 367 operates in this circuit and at armatures 368 and 369 and their respective working contacts closes points in the circuit from the alternating current source to trunk conductors 1 and 2, but these conductors are now open at armatures 372 and 373. At armature 370 and its working contact, relay 367 completes an auxiliary locking circuit for itself extending from grounded conductor 382, armature 312 and its resting contact, working contact of armature 370 and said armature, working contact of armature 316 and said armature, winding of relay 367, to battery. This circuit maintains the relay 367 operated when its initial energizing circuit is opened at armature 374 during the repeating of the digit impulses.

When the dial 282 is released and allowed to return to normal, the impulsive circuit to relay 371 is opened three times in accordance with the first digit. Each time the dial contacts are broken, relay 371 releases and at armatures 372 and 373 and their respective resting contacts the alternating current source is connected to conductors 1 and 2, whereby three short impulses of alternating current are transmitted over the trunk line to repeater R1 in exchange A. When the dial 282 has returned to normal, the circuit to relays 268 and 272 is broken and these relays release, again closing the circuit for the supervisory relays 274 and 278 and the sleeve relay 303. These relays again operate and the supervisory lamp 215 is again lighted. At armature 273 of relay 272 the battery connection through resistance 283 is removed from the ring conductor and relay 314 again releases, completing the circuit for sleeve relay 303. Relay 314 opens the circuit of relay 367 which also releases.

55 The remaining digits, 2 and 3 are transmitted over the trunk lines in the same manner as described above for the first digit. Relays 274, 278, and 303 release when the dial is moved off-normal and relays 268, 272, 314, 371, and 367 are operated. When the dial 282 returns to normal after the last digit 3 has been transmitted, relays 314, 367, and 371 are released and the sleeve relay 303 and supervisory relays 274 and 278 are again operated, and the supervisory lamp 215 re-

mains lighted until the called subscriber answers.

Referring now to repeater R1 as shown in Fig. 4 of the drawings, the alternating current impulses transmitted over conductors 1 and 2 by the trunk circuit TC are received by relay 435 which is operated by each impulse. Each time relay 435 operates it completes a circuit from ground, normally closed springs controlled by armature 413, armature 436 and its working contact, conductor 11, working contact of armature 449 and said armature, normally closed springs controlled by armature 444, winding of relay 488, to battery. Relays 488, 494, and 499 are impulse correcting relays which are provided so that the interruptions in the loop circuit extending to the automatic switch train in exchange A will be of the proper length. Relay 488 operates at the beginning of each impulse in the above traced circuit, and completes a locking circuit for itself from ground at the resting contact of armature 497 and said armature, armature 490 and its working contact, winding of relay 488 to battery. At armature 493 and its resting contact it opens the loop circuit extending to the selector switch IS1. At armature 491 and its working contact it completes a circuit for the upper winding of relay 499 over the normally closed contacts controlled by armature 496. Relay 499 operates and at armature 443 and its working contact, completes a circuit for the upper winding of relay 494. At armature 442 and its resting contact it opens the short-circuit around its lower winding and at armature 444 and its working contact it transfers the impulsive circuit from relay 435 to its own winding so that relay 499 will not release until the end of the alternating current impulse. Relay 494 operates and at armature 497 and its resting contact, opens the circuit of relay 488 allowing this relay to release and at armature 493 and its resting contact again close the loop circuit to the incoming selector, thereby completing the first impulse to the switch. At armature 498, relay 494 opens the short-circuit of its lower winding. At armature 496 and its working contact it completes the above traced locking circuit from the impulse conductor 11 to the upper winding of relay 499.

Thus, relays 499 and 494 are locked operated until the end of the alternating current impulse, if this impulse has not already ended before the operation of relay 494. If the alternating current received was shorter than desired, the circuit of relay 499 is opened at armature 496 as soon as relay 494 operates. Relay 499, therefore, releases and at armature 443 opens the circuit of relay 494 and allows this relay to release. From the above explanation, it is apparent that the loop circuit extending to the incoming selector switch IS1 is opened for the same duration of time for

- each impulse, namely the time required for relays 499 and 494 to operate and for relay 488 to release. The outgoing impulses to the selector switch are uniform irrespective of 5 the length of the alternating current impulses received. The first time relay 499 operated it completed a circuit from ground, armature 441 and its working contact, conductor 16, winding of relay 415 to battery. 10 Relay 415 operates in this circuit and at armature 418 and its working contact short-circuits the upper-left-hand winding of repeating coil 437 to improve the operation of the impulse-responding relay 435. 15 It might be well to point out at this time that when relay 445 operated, when the repeater R1 was first seized and at armature 447 grounded conductor 6, relay 419 operated in a circuit from the grounded conductor, 20 winding of relay 419, resistance 420 to battery, and relay 400 was operated in a circuit from the grounded conductor 6, winding of relay 400, resistance 434 to battery. Each time relay 499 operates responsive to the digit 25 impulses, a circuit is completed from ground at armature 433 of relay 430 and the resting contact of said armature, conductor 22, armature 440 and its working contact, working contact of armature 455 and said armature, conductor 20, to the lower terminal of 30 the winding of relay 400. This ground shunts out the battery through resistance 434 and shunts the winding of relay 400, thereby making this relay slow-to-release so that it 35 will not release during the momentary short-circuit of its winding when the dialling impulses are being received.
- Referring now to Figs. 5 and 6 of the drawings, the circuit of line relay 500 of incoming selector IS1 is opened each time relay 488 of the impulse correcting relays in repeater R1 is operated in accordance with the digit impulses, and at armature 501 and its resting contact relay 500 completes a circuit from ground, armature 513 and its resting contact, armature 501 and its resting contact, armature 504 and its working contact, winding of series relay 505, winding of vertical magnet 517 to battery. Since the 45 first digit dialled was three, the shaft and wipers of selector IS1 will be raised to a position opposite the third level of the bank. Relay 505 operates in series with the vertical magnet and at armature 506 and its 50 working contact completes a circuit from ground at the working contact of armature 503 and said armature, armature 506 and its working contact, off-normal springs 519, interrupter springs of the rotary magnet, winding of relay 507 to battery. Relay 507 operates and at armature 509 and its working contact prepares the circuit to the rotary magnet. When relay 505 deenergizes at the end of the vertical movement of the 55 switch, a circuit is completed for the rotary magnet from ground at armature 503, armature 506 and its resting contact, armature 509 and its working contact, winding of rotary magnet 518 to battery. The rotary magnet operates and rotates the wipers into engagement with the first set of contacts in the bank. At the same time it opens its interrupter springs, thereby opening the energizing circuit of relay 507, allowing this relay to release and open the rotary magnet circuit. 70 In case the first trunk in the third level is busy, test wiper 521 will encounter a grounded bank contact and relay 507 will be again operated in a circuit from ground on test wiper 521, armature 512 and its resting contact, off-normal springs 519, interrupter springs of the rotary magnet 518, winding of relay 507 to battery. Relay 507 again operates to complete the rotary magnet circuit which energizes and rotates the wipers into engagement with the second set of bank contacts. The operation of the rotary magnet again opens the circuit of relay 507 and allows this relay to release. 75
- The above inter-action between stepping relay 507 and the rotary magnet 518 continues until test wiper 521 is rotated into engagement with a bank contact associated with an idle trunk. As soon as ground is removed from test wiper 521, relay 510, which has been shunted by this ground during the rotation of the shaft and wipers, operates in series with the stepping relay 507. At armatures 511 and 514 and their respective resting contacts it disconnects line relay 500 and at the working contacts of these armatures it switches through the incoming line to the line wipers 520 and 522. At armature 512 and its working contact a locking circuit is prepared for switching relay 510 and at armature 513 and its resting contact ground is removed from the armature of the line relay to prevent the release of the switch at this time. Relay 500 deenergizes and at armature 501 and its working contact opens the circuit of release relay 502. Relay 502 is slow-to-release and remains operated until ground has been returned over test wiper 521 to maintain relay 510 operated. Relay 502 then releases and at armature 503 and its working contact opens the initial energizing circuit of relay 510, and at armature 504 and its resting contact prepares a point in the release circuit of the switch. 90
- It will be assumed that the connector C1 shown in Fig. 6 of the drawing was selected by the incoming selector IS1 over bank contacts 552, 553, and 554. As soon as switching relay 510 of the selector is operated and switches through the incoming line, line relay 607 operates over the incoming loop and at armature 608 and its working contact closes a circuit for release relay 609. Release relay 609 operates and at armature 95 100 105 110 115 120 125 130

610 and its working contact connects ground to the release trunk conductor which is extended over conductor 33, bank contact 553 and test wiper 521 to complete the above 5 mentioned locking circuit for the switching relay 510 of the selector. Relay 600 which is included in the circuit of line relay 607 is a differential relay and does not operate at this time. At armature 611 and its working contact release relay 609 prepares the impulsive circuit and at armature 612 and its working contact it prepares a locking circuit for relays 615 and 631.

When the incoming loop is interrupted at 15 armature 493 of relay 488 in repeater R1, line relay 607 releases and completes a circuit from ground, armature 608 and its resting contact, armature 611 and its working contact, off-normal contacts 643, winding of 20 series relay 613, winding of vertical magnet 641 to battery. At the first vertical step the off-normal springs are operated and thereafter the impulsive circuit extends over off-normal contacts 642 and armature 614 and 25 its working contact of the series relay 613 which operates in series with the vertical magnet at the first impulse. Since the second digit of the called telephone number was assumed to be 2, the shaft and wipers of the 30 connector switch are raised opposite the second level of the bank. When relay 607 remains energized at the end of this digit, series relay 613 releases and at armature 614 and its resting contact prepares the circuit 35 for the rotary magnet. When relay 607 releases responsive to the first impulse of the last digit, a circuit is completed from ground, armature 608 and its resting contact, armature 611 and its working contact, off-normal 40 springs 642, armature 614 and its resting contact, resting contact of armature 624 and said armature, armature 636 and its resting contact, winding of rotary magnet 644 to battery and in parallel with the rotary magnet 45 through the winding of relay 627 to battery. Relay 627 operates in this circuit and at armature 629 and its working contact completes a circuit for the rotary magnet independent of armature 624 of relay 619. The rotary magnet is energized in this circuit at each 50 impulse of the last digit, which in this case was assumed to be 3, and rotates the wipers of the switch into engagement with the third set of bank contacts in the second level. At armature 628 and its working contact relay 627 prepares a test circuit to relay 619. At armature 630 and its resting contact it opens 55 a point in the energizing circuit of relay 615.

It will first be assumed that subscriber T3 60 is already engaged in a conversation when the wipers of connector C1 are operated into engagement with bank contacts 648, 649, and 650. In this case there will be a ground potential on test bank contact 649, and test relay 619 will operate in a circuit extending

from grounded bank contact 649, test wiper 646, armature 628 and its working contact, winding of relay 619 to battery. Relay 619 operates in this circuit and at armature 626 and its working contact connects up the busy-tone to the incoming line conductor 34 over conductor 652, resting contact of armature 637 and said armature, working contact of armature 626 and said armature, and through the line condenser to conductor 34. At armature 625 and its working contact an energizing circuit is prepared for relay 615. At armature 620 and its working contact relay 619 prepares a locking circuit for itself which becomes effective as soon as the slow-to-release relay 627 deenergizes. At armature 621 and its resting contact the circuit of the switching relay 631 is opened and at armature 623 and its resting contact a point is opened in the circuit of the battery reversing relay 602.

When relay 627 releases it completes the locking circuit of relay 619 at the normally closed springs controlled by armature 628, and at armature 630 and its resting contact 90 completes an energizing circuit for relay 615. Relay 615 operates and at armatures 616 and 618 and their respective resting contacts it opens the ringing circuit and at the working contacts of these armatures it closes points in the talking conductors. At armature 617 and its working contact it completes a locking circuit for itself to ground at armature 612 of release relay 609 by way of armature 601 of the differential relay 600.

The busy tone is transmitted to the operator at the manual exchange through repeating coil 437 of repeater R1, over the trunk line and through repeating coil 318 of the trunk circuit TC to the cord circuit CC and operator's telephone circuit OTC. When the operator at the manual exchange hears this tone she knows that the wanted subscriber is already engaged in a telephone connection. In case she wishes to offer the call to the wanted subscriber, she momentarily operates the toll offering key 286, thereby completing a circuit from ground, key springs 277, windings of relays 272 and 268 to battery. Relays 272 and 268 operate in this circuit and at armature 270 the circuit of the supervisory relays 274 and 278 and the sleeve relay 303 of the trunk circuit TC is opened, and these relays release. At armature 273 and its working contact a circuit is completed from battery, resistances 284 and 285 in multiple, key spring 276, working contact of armature 273 and said armature, conductor 223, armature 206 and its working contact, ring of plug P and jack J, lower-left-hand winding of repeating coil 318, winding of 314, upper winding of relay 310, resting contact of armature 304 and said armature, to ground, relay 303 having been released as described above.

Relay 314 operates in the above circuit and

the differential relay 310 also operates in this circuit from the battery feed through the resistances 284 and 285 in multiple. When sleeve relay 303 released the slow-to-release relay 307 was operated from ground at the jack springs 300. At armature 309 and its working contact, relay 307 closes a locking circuit for the lower winding of relay 310, and at armature 308 and its working contact 5 completes a circuit extending from ground, armature 311 and its working contact, working contact of armature 308 and said armature, winding of relay 367 to battery. Relay 367 operates and at armatures 368 and 369 10 and their respective working contacts connects the alternating current source to the trunk conductors 1 and 2. As soon as relay 310 operated it closed a shunting circuit for the winding of relay 307 extending from jack 15 springs 300, armature 312 and its working contact, to the upper terminal of the winding of relay 307. Resistance 384 is provided to prevent the short-circuiting of the battery. Relay 307 is made slow-to-release by a copper slug on the heel end of its core and is 20 further slow-to-release due to its short-circuited winding and, therefore, an appreciable time elapses before this relay will release. When it finally releases it opens the 25 locking circuit of relay 310 at armature 309 and its working contact and allows this relay to release, thereby reoperating sleeve relay 303 and the supervisory relays 274 and 278 in the position circuit. The release of relay 307 30 opens the circuit of the impulse sending relay 367 at armature 308 and its working contact and relay 367 thereupon releases and at armatures 368 and 369 opens the connection of the alternating current source to the trunk line 35 conductors 1 and 2. The length of the toll offering impulse is, therefore, governed by the time required for the slow-to-release relay 307 and relay 367 to deenergize. Referring now to repeater R1 shown in Fig. 4 of the drawings, when the toll-offering alternating-current impulse is received over trunk conductors 1 and 2, relay 435 is operated and at armature 436 and its working contact completes a circuit from ground at 40 the normally closed springs controlled by armature 413, armature 436 and its working contact, conductor 11, working contact of armature 449 and said armature, normally closed springs controlled by armature 444, 45 winding of relay 488 to battery. Relay 488 operates and at armature 490 and its working contact completes a locking circuit for itself to ground at armature 497 of relay 494. At armature 491 and its working contact it 50 completes the circuit for the upper winding of relay 499. Relay 499 operates, at armature 443 and its working contact completes an energizing circuit for relay 494, and at armature 444 and its working contact prepares 55 a locking circuit for itself. Relay 494 operates and at armature 497 and its resting contact it opens the locking circuit of relay 488, which thereupon releases. At armature 496 and its working contact, relay 494 completes a locking circuit for relay 499 and the latter 60 relay remains locked up to conductor 11 until the end of the toll offering impulse. At armature 441 and its working contact, relay 499 completes an operating circuit for relay 415. Relay 415 operates and at armature 417 and its working contact prepares a locking circuit for the slow-to-release relay 405. When relay 499 operated it completed a circuit at armature 440 extending from ground at armature 433 of relay 430, conductor 22, armature 440 and its working contact, working contact of armature 455 and said armature, conductor 20, to the lower terminal of the winding of relay 400 thereby shunting this relay and allowing it to release. When relay 400 releases it extends the ground on conductor 20 through armature 401 and its resting contact to the lower terminal of the winding of relay 419, thereby shunting this relay. At armature 403 and 70 its resting contact it completes an operating circuit for relay 405 from the grounded conductor 20. Relay 405 operates and at armature 406 and its working contact completes a locking circuit for itself to the grounded conductor 6, through armature 417 of relay 415. Relays 400 and 419 are so adjusted and the toll offering impulse is so timed that relay 499 remains operated a sufficient length of 75 time so that the shunted relay 400 will release and operate relay 405. The impulse ends before relay 419, which is shunted upon the release of relay 400, has had time to de-energize. At the end of the toll offering impulse, relay 435 releases and at armature 436 and its working contact opens the locking circuit of relay 499. Relay 499 releases and 80 opens the circuit of relay 494 at armature 443 and its working contact. At armature 441 and its working contact it opens the circuit of slow-to-release relay 415, and at armature 440 and its working contact it opens the shunting circuit of relays 400 and 419. Relay 400 again operates and opens the shunting circuit of relay 419 at armature 401 and its 85 resting contact. At armature 404 and its working contact it completes a circuit extending from ground at armature 433 of relay 430 and the resting contact of this armature, armature 404 and its working contact, resting contact of armature 414 and said armature, armature 409 and its working contact, conductor 21, working contact of armature 456 and said armature, armature 446 and its working contact, conductor 25, armature 511 and its working contact (Fig. 5), wiper 520 and bank contact 552, conductor 32, upper winding of differential relay 600 (Fig. 6), normally closed springs controlled by armature 603, upper winding of line relay 607 to 90

battery. The lower winding of relay 600 is thereby shunted and this relay energizes over its upper winding. Relay 600 operates and at armature 601 and its working contact it completes a circuit for switching relay 631 extending from ground at armature 612 of the release relay 609 and through the working contact of this armature, armature 601 and its working contact, lower winding of switching relay 631 to battery. Relay 631 operates and at armature 635 and its working contact completes a locking circuit for itself from ground at armature 612 of the release relay 609. At armature 637 and its resting contact it opens a point in the busy-tone circuit and at armatures 632 and 638 and their respective working contacts it completes the talking circuit over wipers 645 and 647 and bank contacts 648 and 650 to the called subscriber's line. At armature 634 and its working contact it transfers the locking circuit of relay 619 to the ground potential which is present on test wiper 646, due to the previously established connection.

25 Since relay 619 remains operated, it is apparent that the talking connection to the already established connection, in which subscriber T3 is engaged, is established by connector C1 without any battery connections to the line since the back-bridge relay 602 has been disconnected at armatures 626 and 623 by the operation of relay 619. Thus, the operator can cause the connector C1 to cut-in on the busy line without any disagreeable

30 noises and can offer the call to the wanted subscriber. The locking circuit of relay 619 is transferred to the ground potential which is present on bank contact 649 so that in effect the connector C1 will camp on the busy line

35 and wait for the wanted subscriber to release the already established connection.

Referring now to the point where relay 400 again operated to complete the circuit for the ground connection to negative talking conductor, the duration of this ground connection is determined by the time required for the slow-to-release relay 415 and the slow-to-release relay 405 to deenergize. When relay 499 releases it opens the operating circuit of relay 415 at armature 441 and its working contact. Relay 415 releases after an interval and at armature 417 and its working contact opens the locking circuit of relay 405. After an interval relay 405 releases and at armature 409 and its working contact opens the circuit over which ground was connected to the negative talking conductor as described above.

In case the subscriber at substation T3, 60 when informed of the call which is waiting from the manual exchange, desires to continue with the present conversation and instructs the operator to release the other call, the operator at the manual exchange will 65 remove the plug P from the jack J and bring

about the release of ⁷⁰ the equipment which has been used in the establishment of the connection. The method in which the release of the equipment is brought about will be explained later. It will be assumed that subscriber at substation T3 wishes to accept the toll call from the manual board and hangs up his receiver to release the already established connection. As soon as ground is removed from test bank contact 649 by the release of the established connection, relay 619 is released and at armature 625 and its working contact it opens the initial energizing circuit of the ring-cut-off relay 615, but this relay remains operated over its armature 617 from ground at armature 612 of release relay 609. At armatures 623 and 626 of relay 619, the back-bridge relay 602 is again connected to the line wipers and at armature 622 and its resting contact ground is connected to test wiper 646 to make the call line busy to other switches. When the established connection has been released, the called subscriber again lifts his receiver thereby completing a direct current path through his substation and allowing the back-bridge relay 602 to operate and reverse the battery connections to the incoming line. Relay 602 at armature 606 and its working contact also completes another point in the locking circuit of relays 631 and 615 so that these relays will not release in case the called subscriber does not replace his receiver after the operator has released the connection.

The reversal of the battery connections to the line at connector C1 reverses the current through the lower winding of relay 471 in repeater R1, and as the two windings now assist each other this relay operates. At armature 472 and its working contact, relay 471 completes a circuit from the grounded conductor 6, normally closed springs controlled by armature 431 of relay 430, conductor 4, working contact of armature 472 and said armature, winding of relay 473 to battery. Relay 473 operates and at armature 478 and its working contact shunts the impulsing springs on relay 488 to prevent the opening of the loop circuit to connector C1, at armature 477 and its working contact it prepares a circuit for relay 480, at armature 475 and its working contact it prepares a circuit for the impulse sending relay 423, and at armature 476 and its working contact it completes a circuit for relay 488 of the impulse correcting relays extending from ground, normally closed springs controlled by armature 413 of relay 410, armature 436 and its resting contact, conductor 10, armature 476 and its working contact, resting contact of armature 483 and said armature, normally closed springs controlled by armature 444, winding of relay 488 to battery. Relay 488 operates and at armature 491 and its working contact completes a circuit for relay 499.

Relay 499 operates and at armature 443 and its working contact completes a circuit for relay 494. At armature 444 and its working contact it opens the initial energizing circuit of relay 488 and at the working contact of this armature it prepares a locking circuit for itself. Relay 494 operates and at armature 496 and its working contact, completes the locking circuit of relay 499 to the ground-
 5 ed conductor 10, at armature 497 and its resting contact it opens the locking circuit of relay 488 allowing this relay to release. Relay 499 in operating also completes a circuit for relay 480 at armature 441 and its working contact extending over armature 477 of relay 473. Relay 480 operates and at armature 484 and its working contact locks itself to the grounded conductor 6. At armature 485 and its working contact it completes a
 10 second shunt circuit for the impulsing springs of relay 488. At armature 486 and its working contact it short-circuits the lower winding of relay 494 and at armature 487 and its working contact short-circuits the
 15 lower winding of relay 499.

When relay 488 operated responsive to the operation of relay 473, it completed a circuit from the grounded conductor 10, armature 475 and its working contact, working contact 30 of armature 492 and said armature, conductor 9, upper winding of relay 423 to battery. Relay 423 operates and at armatures 424 and 425 and their respective working contacts it connects the alternating current source 35 through the frequency doubling transformer 35 to the trunk conductors 1 and 2 to transmit an impulse of alternating current over the trunk line for answering supervision. When relay 480 operated it opened the locking circuit of relay 499 at armature 483 and its resting contact but the lower winding of this relay is short-circuited at armature 487 and the relay is, therefore, slow-to-release. Relay 499 releases after an interval and at armature 443 and its working contact it opens the energizing circuit of relay 494 which is also slow-to-release, due to its short-circuited lower winding. After a short interval relay 494 releases. The length of the alternating 40 current impulse transmitted over the trunk line to the manual exchange is, therefore, governed by the time required for relays 499 and 494 to operate and for relay 488 to release, since the circuit of the impulse transmitting 45 relay 423 is opened at armature 492 and its working contact as soon as relay 488 releases. The impulse correcting relays 488, 494, and 499 are now restored to normal and relays 471, 473, and 480 remain operated.

50 The alternating current impulse which was transmitted over the trunk line responsive to the answering of the called subscriber momentarily operates the alternating-current impulse-receiving relay 320 in the trunk circuit TC in Fig. 3 of the drawings. At arm-
 55

ture 321 and its working contact, relay 320 completes a circuit from ground, working contact of armature 321 and said armature, armature 326 and its working contact, armature 338 and its resting contact, normally closed springs controlled by armature 346, upper winding of relay 343 to battery. Relay 343 operates and at armature 345 and its working contact completes a locking circuit for its two windings in series extending through resting contact of armature 355 and said armature, to ground at jack springs 300. At armature 344 and its resting contact it removes ground from the low resistance winding of relay 303, thereby bringing about the release of relays 274 and 278 in the operator's position circuit and extinguishing the supervisory lamp 215 to inform the operator that the called subscriber has answered. At armature 346, relay 343 opens its initial energizing circuit and at the working contact of this armature transfers the ground from the impulse receiving relay to the upper terminal of the winding of relay 347. However, the answering supervisory impulse received is not of sufficient length to release relay 347 and this shunting circuit is opened at armature 321 and its working contact by the cessation of the impulse before relay 347 releases. Upon noting the extinguishing of the lamp 215, the operator restores the key K to its normal position, thereby releasing relay 200. Relay 200 in releasing connects the talking conductors through from plug P1 to plug P and also releases the operator's position circuit PC. The calling subscriber has now been connected to the desired called subscriber and the conversation may take place, the talking circuit including repeating coil 318 in trunk circuit TC and the repeating coil 437 in repeater R1.

Returning now to the point where the wipers of connector C1 were operated into engagement with bank contacts 648, 649, and 650, it will now be assumed that the subscriber T3 is not engaged in any telephone connection at this time. In this case there will be no ground potential present on bank contact 649 and the busy relay 619 will not be operated. A short interval after the cessation of the dialling impulses, relay 627 releases and at armature 628 and its resting contact completes a circuit from ground at the working contact of armature 610 and said armature, resting contact of armature 621 and said armature, upper winding of switching relay 631, resting contact of armature 628 and said armature, wiper 646 and bank contact, 649, to battery through the cut-off relay of the called subscriber's lineswitch. Relay 631 operates in this circuit in series with the cut-off relay and at armature 635 and its working contact completes a locking circuit for its lower winding. At armature 633 and its working contact direct ground is connected

to test wiper 646 to make the called line busy to other switches and also to maintain the cut-off relay of the lineswitch operated. At armature 636 and its resting contact relay 631 opens a point in the circuit to the rotary magnet, and at armatures 632 and 638 and their respective working contacts it completes the ringing circuit to the called line. This ringing circuit extends from the ringing lead 651, upper winding of ring-cut-off relay 615, resting contact of armature 616 and said armature, working contact of armature 632 and said armature, wiper 645, bank contact 648, line conductor extending to the called station, 15 the bell and condenser at the called station, the second line conductor, bank contact 650, wiper 647, armature 638 and its working contact, armature 618 and its resting contact to ground. Ringing current is intermittently transmitted over this circuit until the called subscriber lifts his receiver, thereby short-circuiting the bell and condenser at this station and completing a direct current path over the above traced circuit for the upper 25 winding of ring-cut-off relay 615. Ring-cut-off relay 615 operates and at armature 617 and its working contact completes a locking circuit for its lower winding. At armatures 616 and 618 and their resting contacts it opens 30 the ringing circuit and at the working contacts of these armatures it completes the talking circuit to the called station.

Responsive to the completion of the talking circuit, back-bridge relay 602 operates over the called subscriber's loop and at armatures 603 and 604 reverses the battery connections to the incoming line conductors. At armature 605 and its resting contact a point is opened in the release circuit of the connector switch. The reversal of the battery connections to the incoming line conductor causes the repeater R1 to transmit a short impulse of alternating current over the trunk line to extinguish the supervisory lamp at 45 the operator's position, in the manner described above. The operator then releases the key K associated with her cord circuit and the talking connection between the calling and called subscribers is established.

When the called subscriber at substation T3 hangs up his receiver at the end of the conversation, back-bridge relay 602 releases and again restores the battery connections to the incoming line conductors to normal. The reversal of current through the lower winding of relay 471 in repeater R1 causes this relay to release, and at armature 472 and its working contact it opens the circuit of relay 473. Relay 473 releases and at armature 475 and its resting contact it completes a circuit for the impulse transmitting relay 423 extending from the grounded conductor 10, armature 475 and its resting contact, working contact of armature 481 and said armature, conductor 9, upper winding of re-

lay 423 to battery. Relay 423 operates and at armatures 424 and 425 it connects the alternating current source to trunk conductors 1 and 2 extending to the manual exchange to transmit an alternating current impulse as a disconnect signal. At armature 476 and its resting contact, relay 473 completes a circuit from grounded conductor 10, armature 476 and its resting contact, armature 482 and its working contact, armature 495 and its resting contact, winding of relay 488 to battery. At armature 478 and its working contact relay 473 opens one of the shunts around the impulsive springs of relay 488.

Relay 488 operates in the above circuit and at armature 491 and its working contact completes a circuit for relay 499, and at armature 490 and its working contact it completes a locking circuit for itself. Relay 499 operates and at armature 443 and its working contact completes a circuit for relay 494. At armature 441 and its working contact it completes a circuit for relay 415. Relay 494 operates and at armature 495 and its working contact it completes a circuit extending from grounded conductor 10, armature 476 and its resting contact, armature 482 and its working contact, armature 495 and its working contact, armature 465 and its resting contact, upper winding of relay 461 to battery. Relay 461 operates its armature 463 to complete a locking circuit for itself from grounded conductor 6, but does not operate its remaining armatures until the ground is disconnected from the junction of its upper and lower windings. This same ground extends through armature 479 and its resting contact, armature 453 and its working contact, conductor 8, winding of relay 430 to battery. Relay 430 operates in this circuit and at armature 433 and its resting contact removes ground from conductor 22 to prevent the release of relays 400 and 419 and the operation of relay 405.

At armature 497 and its resting contact 494 opens the locking circuit of relay 488 and allows this relay to release. At the normally closed springs controlled by armature 496 it opens the energizing circuit of relay 499. Relay 499 has its lower winding short-circuited at armature 487 and its working contact and is, therefore, slow-to-release. When relay 499 releases it opens the circuit of relay 494 at armature 443 and its working contact, and at armature 441 it opens the circuit of relay 415. Relay 494 is also slow-to-release, due to its lower winding being short-circuited at armature 486 and its working contact and a short interval is, therefore, required for this relay to release. When it releases, it removes the ground connection from the junction point of the two windings of relay 461 and allows this relay to operate in its second step and operate all of its armatures. At the back contact of armature 495

130

relay 494 again completes the circuit of relay 488 and this relay again operates in the hereinbefore described manner. The operation of relays 499 and 494 and the release of 5 relays 488, 499 and 494 follow in the same manner as has just been described.

When relay 461 operated in its second step it prepared a circuit at armature 465 and its working contact for relay 458. When relay 10 494 is operated during the second complete operation of the impulse correcting relays 488, 494, and 499, it completes a circuit from the grounded conductor 10, armature 476 and its resting contact, armature 482 and its 15 working contact, armature 495 and its working contact, armature 465 and its working contact, conductor 19, armature 429 and its resting contact, conductor 18, winding of relay 458 to battery. Relay 458 operates in this 20 circuit and at the normally closed springs controlled by armature 459 it opens the locking circuit of relay 480 and at the normally closed springs controlled by armature 460 it opens the locking circuit of relay 461. Both 25 of these relays, together with relay 458, remain operated over the circuit just described as long as relay 494 of the impulse correcting relays remains operated. When relay 494 again releases, the ground connection to 30 relays 458, 461, and 480 is opened and these relays release. Relay 458 is made slow-to-release to insure that relays 461 and 480 will release before relay 458 so that their locking circuit will not be again completed at the 35 normally closed contacts controlled by armatures 459 and 460.

When relay 480 releases, as described above, it opens the circuit of the impulse sending relay 423 at armature 481 and its 40 working contact, thereby terminating the impulse of alternating current which was being transmitted over the trunk line as a disconnect signal to the manual operator. At armature 482 and its working contact it 45 opens the circuit to relay 488 to stop the operation of the impulse correcting relays. At armature 485 and its working contact it opens the second shunt around the impulse springs of relay 488, and at armatures 486 50 and 487 and their respective working contacts it opens the short-circuits around the lower windings of relays 494 and 499. Slow-to-release relays 415 and 430 release after an interval following the final release of relay 499.

When the long alternating current impulse for disconnect supervision transmitted in the manner just described is received at the trunk circuit TC, relay 320 operates and 60 at armature 321 and its working contact it connects ground through armature 326 and its working contact, armature 338 and its resting contact, working contact of armature 346 and said armature, to the upper terminal 65 of the winding of relay 347. A resistance

383 is provided to prevent the short-circuiting of the battery. Relay 347 is made slow-to-release by a copper slug on the heel end of its core and is now shunted by the ground connected to the upper terminal of its winding. 70 The disconnect pulse is so timed that it is of sufficient duration to maintain relay 347 shunted until it releases. When relay 347 releases it completes a circuit for relay 353 extending from ground at armature 344 of relay 343 and the working contact of this armature, armature 349 and its resting contact, armature 332 and its resting contact, upper winding of relay 353 to battery. At armature 350 and its working contact it opens its locking circuit and at armature 352 and its working contact it opens one point in the circuit of the busy visual 302. The busy visual, however, is maintained operated from ground at armature 363 of relay 362. 80

Relay 353 operates in the above traced circuit and at armature 354 and its working contact it completes a locking circuit for its two windings in series from ground at armature 344 of relay 343. At armature 355 and its resting contact it opens the locking circuit of relay 343. The operation of the remaining armatures is without effect at this time. Relay 343 releases when its locking circuit is opened by relay 353 and at armature 344 and its working contact, opens the locking circuit of relay 353 and at the resting contact of this armature it connects ground to the low resistance lower winding of sleeve relay 303 which is extended over the resting contact of armature 315 and said armature, sleeve of jack J and plug P, normally closed springs controlled by armature 203, and to battery through supervisory lamp 215 and resistance 217 in multiple. Supervisory lamp 215 lights to inform the operator that the called subscriber has hung up his receiver. Relay 347 is released only momentarily and again operates as soon as relay 320 releases at the end of the disconnect signal. 100

When the operator notes the lighted condition of the supervisory lamp 215 she removes the plug P from a trunk jack J, thereby opening the circuit of the sleeve relay 303 and opening the jack springs 300. The opening of jack springs 300 removes ground from conductor 382, thereby opening the locking circuit of relay 322 and the circuit of relay 360. Relay 322 releases and at the double contacts 323 and 325 it opens the circuit of relay 347. At armature 329 and its resting contact it completes a circuit extending from ground, armature 329 and its resting contact, armature 341 and its resting contact, armature 364 and its working contact, winding of relay 367 to battery. Relay 367 operates and at armatures 368 and 369 and their respective working contacts it connects the alternating current source to trunk conductors 1 and 2, thereby transmitting an alternating current 115 120 125 130

impulse over the trunk line to release the equipment in the automatic exchange. When relay 360 is deenergized, its weighted spring 361 continues to vibrate for some time and 5 maintains the circuit of relay 362 closed until the armature spring 361 finally comes to rest. Relay 362 is then deenergized and since this relay is somewhat slow-to-release due to the copper slug on the armature end of the core, 10 some time is required before this relay finally releases. When relay 362 releases it opens the circuit of the busy visual at armature 363 and its working contact and at armature 364 and its working contact it opens the circuit of 15 relay 367, allowing this relay to release and disconnect the alternating current source from the trunk conductors 1 and 2, thereby ending the release impulse. All the relays in the trunk circuit TC have now been restored 20 to normal.

When the alternating current release impulse is received at repeater R1 over trunk line conductors 1 and 2, relay 435 responds and at armature 436 and its working contact 25 again completes a circuit for relay 488, thereby starting the operation of the impulse correcting relays. Relay 488 operates and at armature 491 and its working contact completes a circuit for relay 499. At armature 30 490 and its working contact it completes a locking circuit for itself, and at armature 493 and its resting contact it opens the loop circuit extending to the automatic switches. Relay 499 operates and at armature 444 and 35 its working contact it prepares a locking circuit for itself to the conductor 11 which is grounded as long as the alternating current impulse is being received. At armature 443 and its working contact it completes a circuit for relay 494 and at armature 441 it again completes an energizing circuit for relay 415. At armature 440 and its working contact it again completes the shunting circuit for relay 400 extending from ground at 40 armature 433 and the resting contact of this armature, conductor 22, armature 440 and its working contact, working contact of armature 455 and said armature, conductor 20, to the lower terminal of the winding of relay 400.

Relay 494 operates in its energizing circuit and at armature 497 and its resting contact opens the locking circuit of relay 488. At armature 496 and its working contact it completes the locking circuit of relay 499 and 45 relays 499 and 494 remain locked up until relay 435 releases at the end of the alternating current impulse.

Relay 400 releases after an interval since 50 its winding is shunted by ground on conductor 20 and at armature 401 and its resting contact it transfers this ground to the lower terminal of the winding of relay 419. At armature 403 and its resting contact it completes an operating circuit for relay 405 ex-

tending from the grounded conductor 20, resting contact of armature 403 and said armature, lower winding of relay 405 to battery. Relay 405 operates and at armature 406 and its working contact completes a locking circuit for itself extending through armature 417 and its working contact to the grounded conductor 6. This locking circuit was prepared at armature 417 of relay 415 when the latter relay operated responsive to the operation of impulse correcting relay 499. At armature 408 and its working contact relay 405 prepares an energizing circuit for relay 410.

The alternating current impulse which is received to release the equipment in exchange A is of sufficient length so that relay 400 will release due to its shunted winding and transfer the shunting circuit to relay 419 and also to allow relay 419 to release. When relay 419 releases it completes an operating circuit for relay 410 extending from ground, armature 408 and its working contact, resting contact of armature 421 in said armature, winding of relay 410 to battery. Relay 410 operates and at the normally closed contacts controlled by armature 413 it opens the locking circuit of relay 445. Relay 445 releases and at armatures 446 and 457 and their respective working contacts it opens the loop circuit extending to the automatic switches. At armature 449 and its working contact it opens the locking circuit of relays 494 and 499 provided the alternating current impulse has not already terminated and allowed these 100 relays to release. At armature 447 and its working contact, relay 445 removes ground from the release trunk conductor 6 to render the repeater R1 available to selectors in exchange A and to open the locking circuit of relay 405. Relay 405 releases and opens the circuit of relay 410 which also releases. The circuit of relay 415 is opened at armature 441 as soon as relay 499 has released. Since the ground has been removed from conductor 6, relays 400 and 419 can not again operate. All of the relays in the repeater R1 have now been restored to normal.

Referring now to Figs. 5 and 6 of the drawings, when the incoming line to the automatic switches is opened by the release of relay 445 in repeater R1, line relay 607 in connector C1 releases and opens the circuit of release relay 609. After an interval relay 609 releases and at armature 611 and its resting contact completes the circuit for release magnet 639. Release magnet 639 operates and restores the connector switch C1 to normal. At armature 612 and its working contact, release relay 609 opens the locking circuits of switching relay 631 and the ring-cut-off relay 615 and these relays thereupon release. At armature 610 and its working contact, release relay 609 removes ground from the release trunk conductor 33, thereby open-

ing the locking circuit of switching relay 510 of the selector IS1 and allowing this relay to release. Relay 510 at armature 513 and its resting contact completes the circuit for 5 the release magnet 515 of the selector switch IS1. Release magnet 515 operates and restores the selector switch IS1 to normal. All of the apparatus which was used in establishing the connection from the manual operator's position to the subscriber at substation T3 in automatic exchange A has now been released and restored to its normal position.

Call from substation T1 in exchange A to the manual exchange

15 The next case to be assumed is that of a subscriber in the automatic exchange A, such as the subscriber at substation T1, desiring to establish a connection with a subscriber who 20 can be reached only by way of the manual operator at the manual exchange. To establish such a connection, the calling subscriber lifts his receiver and dials the digit 0, thereby 25 establishing a connection to the manual exchange. When the subscriber lifts his receiver, lineswitch LS1, which may be of the well known rotary lineswitch type, automatically rotates to select an idle trunk extending to a local selector, such as S1. It will be assumed that the lineswitch has connected with the trunk accessible over bank contacts 523, 30 524, and 525 and extending to the local selector S1, shown in Fig. 5. Responsive to the seizure of this trunk, line relay 526 of the 35 selector operates over the subscriber's loop and at armature 527 and its working contact, completes a circuit for release relay 528 from ground at the resting contact of armature 539. Relay 528 operates and at armature 529 40 and its working contact grounds the release trunk conductor to hold the lineswitch LS1 operated and also to extend a busy potential over conductor 550 to the test bank contacts of the connectors having access to the line 45 of substation T1. At armature 530 and its working contact it prepares the impulsive circuit to the vertical magnet 543.

As shown by the trunking layout of Fig. 1 of the drawings, the repeaters, such as R1, 50 terminating trunks to the manual exchange are accessible in the tenth level of the selectors. The calling subscriber, therefore, proceeds to dial the digit 0. At each interruption of the loop circuit line relay 526 releases and at armature 527 and its resting contact it transmits an impulse to the vertical magnet from ground, armature 539 and its resting contact, armature 527 and its resting contact, armature 530 and its working 55 contact, winding of series relay 531, winding of vertical magnet 543 to battery. Relay 531 operates at the first impulse and at armature 532 and its working contact, completes an operating circuit for the stepping relay 60 65 533 as soon as off-normal springs 545 are

closed on the first vertical step. Relay 533 operates and at armature 535 and its working contact, prepares a circuit for the rotary magnet which is completed as soon as relay 531 releases shortly after the cessation of the 70 vertical impulses. Responsive to the vertical impulses the shaft and wipers of selector switch S1 are raised to a point opposite the tenth level of the bank. When relay 531 releases at the end of this operation, a circuit 75 is completed from ground at the working contact of armature 529 and this armature, armature 532 and its resting contact, armature 535 and its working contact, winding of rotary magnet 544 to battery. The rotary 80 magnet operates and rotates the wipers of the switch into engagement with the first set of bank contacts in the tenth level. The interrupter springs of the rotary magnet are opened when the magnet energizes, thereby 85 opening the circuit of the stepping relay 533 and allowing this relay to release. In releasing, relay 533 opens the rotary magnet circuit at armature 535 and allows the rotary magnet to deenergize and again complete the circuit 90 for relay 533 in case the trunk available in the first set of bank contacts is busy and a ground potential is present on the test bank contact 555. In this case stepping relay 533 is again 95 energized from ground on the bank contact 555, wiper 547, armature 538 and its resting contact, off-normal contacts 545, interrupter springs of the rotary magnet, winding of relay 533 to battery. Relay 533 operates and at armature 535 again completes the circuit 100 of the rotary magnet causing the wipers to be rotated into engagement with the next set of bank contacts. The energization of the rotary magnet again opens the circuit of stepping relay 533 allowing it to release, and 105 in turn open the rotary magnet circuit. This inter-action between the stepping relay 533 and rotary magnet 544 continues until the wipers are rotated into engagement with a set of bank contacts extending to an idle repeater 110 switch, such as R1. During the automatic rotation of the selector over busy bank contacts, the switching relay 536 is shunted by ground on the test wiper 547.

It will be assumed that the repeater R1 115 shown in Fig. 4 of the drawing, is the first idle repeater available in the 0 level of the selector banks and is the one seized by selector S1. When the selector is rotated into engagement with bank contacts 555, 556, and 557, wiper 547 does not encounter ground potential and the stepping relay 533 is not operated. The switching relay 536 is no longer shunted and operates in series with relay 533 in a circuit extending from ground 120 at the working contact of armature 529 and said armature, winding of switching relay 536, off-normal contacts 545, interrupter springs of the rotary magnet, winding of relay 533 to battery. Relay 533 does not op- 125 130

erate in this circuit. At armatures 537 and 540 and their respective resting contacts, relay 536 disconnects the line relay 526 from the subscriber's loop and at the working contacts of these armatures it switches through the talking conductors to repeater R1 over wipers 546 and 548, bank contacts 556 and 557, and conductors 24 and 28. At armature 538 and its resting contact it prepares a locking circuit for itself which is completed when ground potential is returned from the repeater switch R1.

Line relay 526 is released when it is disconnected from the incoming loop and at armature 527 and its working contact it opens the circuit of release relay 528. Relay 528 is slow-to-release and maintains ground on the release trunk conductor at armature 529 until the holding ground potential mentioned above is returned from repeater switch R1 to maintain switching relay 536 operated and to hold the lineswitch LS1 operated over the release trunk conductor.

Referring now to the repeater shown in Fig. 4 of the drawings, when the subscriber's loop is extended to the repeater over conductors 24 and 28 a circuit is completed for relay 466 extending from conductor 24, conductor 3, upper right-hand winding of repeating coil 437, conductor 13, armature 451 and its resting contact, normally closed springs controlled by armature 464, lower winding of relay 466 to battery and from conductor 28, conductor 23, lower-right-hand winding of repeating coil 437, conductor 14, resting contact of armature 452 and said armature, normally closed springs controlled by armature 462, upper-winding of relay 466 to ground. Relay 466 operates over the incoming loop circuit and at armature 467 and its working contact completes a circuit for the slow-to-release relay 468 extending from ground at armature 447 and the resting contact of this armature, armature 467 and its working contact, winding of relay 468 to battery. Relay 468 energizes and at armature 470 and its working contact it completes a circuit for relay 426. At armature 469 and its working contact it prepares a circuit from the impulse receiving relay 435 to the impulse correcting relays 488, 494, and 499.

Relay 426 operates when its circuit is closed at armature 470, and at armature 44 and its working contact it grounds the release trunk conductor 6. This ground is extended over conductor 26 and bank contact 555 to hold the selector switch S1 and the line-switch LS1 operated and to busy the repeater R1 in the banks of other selectors. Relays 400 and 419 operate in a circuit from the grounded conductor 6 through the windings of these relays and to battery through resistances 434 and 420, respectively. At armature 427 and its working contact, relay 426 completes a circuit extending from ground at the work-

ing contact of armature 427 and said armature, armature 407 and its resting contact, winding of relay 410 to battery. Relay 410 is slow-to-operate and after an interval it operates its armatures and at armature 412 and its working contact completes a circuit from ground at the working contact of armature 427 and said armature, armature 412 and its working contact, resting contact of armature 416 and said armature, lower winding of relay 423 to battery. Relay 423 operates and at armatures 424 and 425 and their respective working contacts it connects the alternating current source to the trunk conductors 1 and 2 to transmit a signalling impulse to the manual exchange. At armature 411 and its working contact, relay 410 completes a circuit from ground at the working contact of armature 427 and said armature, working contact of armature 411 and said armature, upper winding of relay 405 to battery. Relay 405 operates and at armature 408 and its working contact closes a point in the locking circuit of relay 410 which is ineffective at this time since the relay 419 is operated and has opened the circuit at armature 421 and its resting contact. At armature 407 and its resting contact, relay 405 opens the energizing circuit of relay 410 and at the working contact of this armature it completes a locking circuit for itself to ground at armature 427 of relay 426. Relay 410 is somewhat slow-to-release due to the copper slug on the armature end of its core and when it releases after a short interval it opens the circuit of the impulse transmitting relay 423 at armature 412 and its working contact. At armature 411 and its working contact it opens the initial energizing circuit of relay 405, but this relay is now locked up in a circuit through armature 407 and its working contact. Relay 423 releases and at armatures 424 and 425 and their respective working contacts it disconnects the alternating current source from the trunk line to end the alternating-current signalling impulse to the manual exchange.

The short signalling impulse transmitted over trunk line conductors 1 and 2 is received at the trunk circuit TC by relay 320. Relay 320 operates and at armature 321 and its working contact it completes a circuit for relay 330 extending from ground at the working contact of armature 321 and said armature, armature 326 and its resting contact, normally closed springs controlled by armature 337, upper winding of relay 330 to battery. Relay 330 operates its armatures 336 and 335 in this circuit. At armature 336 it prepares a locking circuit for its two windings in series from ground at the normally closed springs 324 of relay 322. At armature 335 and its working contact it completes a circuit from ground at springs 324, working contact of armature 335 and said arm-

- ture, armature 334 and its resting contact, winding of relay 347, resistance 383 to battery. At the end of the alternating current impulse when relay 320 releases and removes 5 ground from the junction point of the two windings of relay 330, relay 330 operates in its second step and at armature 342 and its working contact it completes the circuit for the call lamp 301 extending from ground, 10 armature 329 and its resting contact, working contact of armature 342 and said armature, call lamp 301 to battery. The lamp 301 lights to inform the operator that a call is waiting on the trunk line accessible over jack 15 J. At armature 340 and its working contact, relay 330 prepares an operating circuit for relay 365, at armature 338 and its working contact it prepares a shunting circuit for relay 347, at armature 334 and its resting 20 contact it opens the initial energizing circuit of relay 347, at armature 333 it prepares a point in the locking circuit of relay 347, and at armature 332 and its working contact it prepares a point in the operating circuit of 25 relay 353.
- Relay 347 operates when relay 330 is operated in its first step and at armature 350 and its working contact prepares its locking circuit which is completed when relay 330 30 is completely operated. At armature 351 and its resting contact a point in the circuit of relay 353 is opened, and at armature 352 and its working contact a circuit is completed for the busy visual 302 to make this trunk 35 busy at all operators' positions.
- When the operator notes the lighted condition of the call lamp 301 she inserts the plug P of a cord, such as CC, into jack J and 40 operates key K of its left-hand position to answer the call. Sleeve relay 303 operates over the sleeve of jack J and plug P in series with relay 274 of the position circuit, and at armature 304 and its working contact it completes a circuit for relay 367 extending over 45 the resting contact of armature 328 and said armature, winding of relay 367 to battery. Relay 367 operates and at armatures 368 and 369 and their respective working contacts it connects the alternating current source to the trunk conductors 1 and 2 to transmit an 50 impulse over the trunk line as an answering signal. At armature 370 and its working contact it completes a circuit for relay 322 extending from ground, jack springs 300, 55 armature 312 and its resting contact, working contact of armature 370 and said armature, normally closed springs controlled by armature 327, winding of relay 322 to battery. Relay 322 is slow-to-operate and the time required for this relay to operate governs the 60 length of the alternating current impulse being transmitted by the relay 367. When relay 322 operates it completes a locking circuit for itself at armature 327 and its working contact, at armature 328 and its resting 65 contact it opens the initial energizing circuit of relay 367 and at armature 329 and its resting contact it opens the circuit of the call lamp 301 and also opens a point in a second circuit for relay 367 to prevent a second operation of this relay when relay 362 operates and closes its contacts at armature 364. At the normally closed springs 324, relay 322 opens the locking circuit of relay 330, 70 but at the same time it closes a second locking circuit for this relay extending from ground, jack springs 300, contact 323 of relay 322, armature 336 and its working contact, both windings of relay 330 in series to battery. 75
- When the plug P was inserted into jack J, a circuit was also closed for relay 360 extending from ground, jack springs 300, winding of relay 360 to battery. Relay 360 is equipped with a weighted spring armature and some time is required for this armature to come to rest in engagement with its working contact in order to maintain the circuit of relay 362 closed. Relay 362 is 80 made slow-to-operate and does not operate until the armature spring of relay 360 has come to rest in engagement with its working contact. Relay 362 then operates and at armature 363 and its working contact it completes a second circuit for the busy visual 302, and at armature 364 and its working contact it prepares a circuit for relay 367 which, however, is now open at armature 341 of relay 330. When relay 367 released to end the alternating 85 current impulse it completed a talking circuit through to the repeating coil 318 at the resting contacts of armatures 368 and 369. 90
- The alternating current impulse transmitted over the trunk line when the manual operator answers the call is received at repeater R1 by relay 435. Relay 435 operates responsive to this impulse and at armature 436 and its working contact, completes a circuit from ground at the normally closed springs controlled by armature 413, armature 436 and its working contact, conductor 11, normally closed springs controlled by armature 449, armature 469 and its working contact, normally closed springs controlled by armature 444, winding of relay 488 to battery. Relay 488 operates and completes a locking circuit for itself at armature 490 and its working contact, and at armature 491 and its working contact it completes a 100 circuit for relay 499. Relay 499 operates and at armature 443 and its working contact completes an operating circuit for relay 494. At armature 444 it opens the initial energizing circuit of relay 488 and at the working contact of this armature it prepares a circuit for locking itself energized to the grounded conductor 11 as long as the alternating current impulse is being received. At armature 441 and its working contact it completes a circuit 105 for relay 415 which operates without effect 110
- 115
- 120
- 125
- 130

at this time. It also completes a circuit from ground at armature 441 and the working contact of this armature, resting contact of armature 453 and said armature, resting contact 5 of armature 479 and said armature, armature 465 and its resting contact, upper winding of relay 461 to battery. Relay 494 operates when its circuit is closed at armature 443 of relay 499 and at armature 497 and its 10 resting contact it opens the locking circuit of relay 488, allowing this relay to release. At armature 496 and its working contact it completes the locking circuit from conductor 11 through the winding of relay 499. Relays 15 499 and 494 are, therefore, locked energized until relay 435 deenergizes at the end of the alternating current impulse.

Relay 461 energizes in the above traced circuit and closes its lightly adjusted armature 463, thereby preparing a locking circuit 20 for its two windings in series from the grounded release trunk conductor 6. When relay 435 deenergizes at the end of the alternating current impulse, it opens the locking 25 circuit of relay 499 allowing this relay to release and open the circuit of relay 494. In releasing, relay 499 removes the ground connection from the junction point of the two windings of relay 461, and this relay then 30 operates completely over both of its windings. At armatures 462 and 464 the connections of the battery through line relay 466 to the incoming line conductors from the selector S1 are reversed to reverse the flow of current 35 over the calling subscriber's loop. This reversal of current may be utilized to operate a calling subscriber's meter in case metered service is provided.

The manual operator can now converse 40 with the calling subscriber to determine with whom he desires to speak. After obtaining the desired information the operator completes the call over the other end of the cord circuit CC by means of the plug P1 and over 45 a trunk line which may be similar to the trunk line connecting the manual exchange and the automatic exchange A. When the wanted subscriber answers, the operator restores the key K to its normal position, thereby 50 releasing relay 200 and completing the talking connection between the calling subscriber at substation T1 and the desired called subscriber.

At the end of the conversation when the 55 subscriber at substation T1 replaces his receiver, the loop circuit to relay 466 is broken at the subscriber's station and this relay releases. At armature 467 and its working contact it opens the circuit of release relay 468 60 and at the resting contact of this armature it completes a circuit from ground, armature 447 and its resting contact, armature 467 and its resting contact, conductor 7, armature 428 and its working contact, winding of relay 430 65 to battery and in multiple therewith over

conductor 8, resting contact of armature 448 and said armature, conductor 9, upper winding of relay 423 to battery. Relay 423, in operating, connects the alternating current source to the trunk conductors 1 and 2 at armatures 424 and 425 and their working contacts. Relay 430 operates and at armature 432 and its working contact closes a circuit for relay 423 independent of armature 428 of relay 426.

A short interval after its circuit is opened by relay 466, relay 468 releases and at armature 470 and its working contact opens the circuit of relay 426 which also releases. Relay 426, in releasing, at armature 428 and its working contact opens the circuit of relay 430 but this relay is slow-to-release and maintains the circuit of relay 423 closed at armature 432 for a short time after its own circuit is opened at armature 428. Relay 426 80 at armature 44 and its working contact disconnects ground from the release trunk conductor 6 thereby removing ground potential from the release trunk conductor 26 extending to the selector switch S1 and allowing the selector to release as will be described later. The removal of ground from conductor 6 also opens the circuit of relays 400 and 419 and allows these relays to release. At armature 427 and its working contact, relay 426 opens the locking circuit of relay 405, which releases after a short interval.

A short time after its circuit is opened at armature 428, relay 430 releases and at armature 432 and its working contact is opened 100 the circuit of relay 423, allowing this relay to release and disconnect the alternating current source from the trunk conductors 1 and 2. The removal of ground from the release conductor 6 also opens the locking circuit 105 of the battery reversing relay 461, allowing this relay to restore to normal.

At the local selector S1, switching relay 536 releases when the ground potential is removed from conductor 26 and bank contact 110 555. At armature 539 and its resting contact, it completes a circuit for the release magnet 541 extending from ground, armature 539 and its resting contact, armature 527 and its resting contact, armature 530 and its resting 115 contact, off-normal contacts 542, winding of release magnet 541 to battery. The release magnet operates in this circuit and restores the selector switch S1 to normal. The circuit of release magnet is opened at off-normal contacts 542 when the switch reaches its 120 normal position. All of the equipment in automatic exchange A which was used in the establishment of the connection has now been restored to normal.

At the manual exchange, relay 320 responds to the alternating current impulse which was transmitted over the trunk line by repeater R1 when the calling subscriber at substation T1 replaced his receiver, and 130

at armature 321 and its working contact it completes a circuit from ground at the working contact of this armature and said armature, armature 326 and its working contact, 5 armature 338 and its working contact, to the upper terminal of the winding of relay 347, thereby shunting this relay and causing it to release. Resistance 383 is provided to prevent the short-circuiting of the battery. 10 Relay 347 in releasing opens one point in the circuit of busy visual 302 at armature 352 and its working contact, at armature 351 and its resting contact it extends the circuit from grounded armature 321 to winding of 15 relay 353, at armature 350 and its working contact it opens its own locking circuit, at armature 348 and its resting contact it connects ground from armature 344 through the low resistance winding of sleeve relay 20 303, thereby lighting the supervisory lamp 215 at the operator's position to inform the operator that the calling party has disconnected, and at armature 349 and its resting contact it prepares a locking circuit for relay 353. 25 Relay 353 operates in the above traced circuit over its upper winding which is only of sufficient strength to operate its armature 357, thereby completing a circuit from ground, armature 340 and its working contact, armature 357 and its working contact, armature 358 and its resting contact, winding of relay 365 to battery. Relay 365 operates and at armature 366 and its working 30 contact prepares an operating circuit for relay 367. At the end of the release impulse, relay 320 releases and removes ground from the junction point of the two windings of relay 353 and this relay operates completely. 35 At armature 354 and its working contact it locks energized through armature 349 and its resting contact and armature 332 and its working contact to ground. At armature 356 and its resting contact the original energizing circuit of relay 353 is opened, at armature 358 and its resting contact the circuit of relay 365 is opened, and at armature 359 and its working contact the circuit for relay 367 is completed from ground at the 40 working contact of armature 366, working contact of armature 359 and said armature, winding of relay 367 to battery. Relay 367 operates in this circuit and at armatures 368 and 369 and their respective working 45 contacts it connects the alternating current source to the trunk line conductors 1 and 2 to transmit a seizing pulse to the automatic exchange. Relay 365 is slow-to-release and maintains the circuit of relay 367 closed for a short interval after its own circuit is 50 opened at armature 358 of relay 353. When it finally releases it opens the circuit of relay 367 at armature 366 and its working contact, allowing this relay to release to terminate 55 the alternating current seizing impulse.

The seizing impulse, which is sent out by the trunk circuit TC responsive to the receipt of the disconnect signal when the calling subscriber has replaced his receiver, causes the repeater R1 in exchange A to be again prepared for operation in the same manner as has been previously described in connection with a call from the manual exchange to the automatic exchange A. The signal causes the operation of relay 435, which at armature 436 and its working contact completes the circuit for the lower winding of relay 445. Relay 445 operates its armature 450 to complete a locking circuit for its two windings in series and at the end of the impulse when ground is removed from the junction point of the two windings the relay completely operates over this locking circuit and operates all of its armatures. At armature 447 and its working contact ground is connected to conductor 6 and the release trunk conductor 26 to make the repeater busy to selectors in exchange A. The ground extended over conductor 6 brings about the operation of relays 400 and 419 in the manner previously described. At armature 449 and its working contact a circuit is prepared for the impulse correcting relays 488, 494, and 499, at armature 451 and its working contact the loop circuit is closed to the incoming selector IS1 from conductor 25, working contact of armature 446 and said armature, conductor 3, upper-right-hand winding of repeating coil 437, conductor 13, armature 451 and its working contact, lower winding of supervisory relay 471, armature 493 and its resting contact, conductor 14, lower-right-hand winding of repeating coil 437, conductor 23, armature 457 and its working contact, to conductor 27 extending to the incoming selector. At armature 454 and its resting contact the circuit of relay 458 is opened, at armature 455 and its working contact a shunting circuit is prepared for relays 400 and 419, and at armature 456 and its working contact a circuit for grounding the negative line conductor for the toll offering operation is prepared. 105 From the foregoing it is seen that when the calling subscriber replaces his receiver at the end of the conversation, the repeater R1 operates to transmit a disconnect signal over the trunk line to inform the manual operator that the calling subscriber has disconnected. This signal is received at trunk circuit TC which operates to light the supervisory lamp at the operator's position and also in turn returns a seizing signal to the repeater R1 to again prepare this repeater and the associated incoming selector for operation. 110 The circuits are arranged in this manner so that when the manual operator removes the plug P from the jack J responsive to the lighting of the supervisory lamp and the trunk circuit TC transmits a release signal 115 120 125 130

over the trunk line as will be explained presently, this release signal will not again seize the repeater R1 and incoming selector IS1 and maintain these switches permanently 5 busy.

When the operator at the manual exchange removes the plug P from jack J after noting the lighted condition of the supervisory lamp 215, the circuit of sleeve relay 303 is broken 10 and this relay releases. Ground is removed from conductor 382 at the jack springs 300, thereby opening the circuit of relays 322, 360, and 330. Relay 330 is the first to release and at armature 341 and its resting contact it 15 prepares a circuit for relay 367 and at armature 332 and its working contact it opens the locking circuit of relay 353 thereby allowing this relay to release. A short time later relay 322 releases and at armature 329 20 and its resting contact it completes the circuit for relay 367 from ground at armature 329, resting contact of this armature, armature 341 and its resting contact, armature 364 and its working contact, winding of 25 relay 367 to battery. Relay 367 operates and at armatures 368 and 369 and their working contacts it connects the alternating current source to trunk line conductors 1 and 2 to transmit an alternating current impulse for 30 releasing the equipment in the automatic exchange. Relay 353 releases without effect when its circuit is opened at armature 332 of relay 330. Relay 360 has a weighted spring armature 361 and this spring continues to vibrate for some time after the circuit of relay 360 is opened at jack springs 300. When the armature finally comes to 35 rest it opens the circuit of relay 362 which is also slow-to-release due to the copper slug 40 on the armature end of its core. Relay 362 releases after an interval and at armature 364 and its working contact it opens the circuit of relay 367, allowing this relay to release and disconnect the alternating current 45 source from the trunk line thereby ending the release impulse. At armature 363 and its working contact, relay 362 opens the circuit of the busy visual 302. All the equipment at the manual end of the inter-office trunk line 50 has now been restored to normal.

At the exchange A the relatively long release impulse operates relay 435 which completes a circuit from ground at the normally closed springs controlled by armature 413, 55 armature 436 and its working contact, conductor 11, working contact of armature 449 and said armature, normally closed springs controlled by armature 444, winding of relay 488 to battery. Relay 488 operates and at 60 armature 491 and its working contact completes the circuit of relay 499. At armature 490 and its working contact it completes its own locking circuit, and at armature 493 and its resting contact it opens the loop circuit 65 extending to the incoming selector. Relay

499 operates and at armature 444 and its working contact prepares a circuit for locking itself energized to the conductor 11 which is grounded as long as the release impulse is being received. At armature 443 and its 70 working contact it completes the circuit for relay 494, at armature 441 and its working contact it closes an energizing circuit for relay 415, and at armature 440 and its working contact it completes the shunting circuit for relay 400 and relay 419. This shunting circuit extends from ground at armature 433 and its resting contact, conductor 22, armature 440 and its working contact, working contact of armature 455 and said armature, conductor 20, to the lower terminal of the winding of relay 400. Relay 494 operates and at armature 496 and its working contact it completes the above described locking circuit for relay 499. At armature 497 and its resting 75 contact it opens the circuit of relay 488 to allow this relay to release. Relays 499 and 494 now remain locked energized as long as ground is maintained on conductor 11 by relay 435. Relay 400 releases after a short interval and at armature 401 and its resting contact it transfers the ground on conductor 20 to the lower terminal of the winding of relay 419. At armature 403 and its resting 80 contact it completes the circuit for relay 405 which operates and locks energized to the grounded conductor 6 through the working contact of armature 417 and said armature and armature 406 and its working contact. 85

Since the alternating current impulse received by repeater R1 for releasing the equipment in the automatic exchange is of sufficient length so that relays 400 and 419 are both released, relay 419 releases after a short interval and at armature 421 and its resting 90 contact completes the circuit to relay 410 from ground at armature 408 of relay 405. Relay 410 energizes and at the normally closed springs controlled by armature 413 it opens the ground connection to the locking circuit of relay 445 but the ground from armature 408 is substituted therefor until relay 405 releases. 95

When relays 499 and 494 release at the 100 termination of the release impulse, the circuit of relay 415 is opened at armature 441 and its working contact and the shunt circuit is removed from relays 400 and 419 at armature 440 and its working contact. Relay 415 releases after an interval and at armature 417 and its working contact it opens the locking 105 circuit of relay 405. Relay 405 releases and at armature 408 and its working contact it opens the circuit of relay 410 and also removes ground from the holding conductor 12, thereby allowing relay 445 to release. Relay 410 is somewhat slow-to-release and maintains the ground disconnected from conductor 12 until relay 445 has had sufficient time to de-energize. Relay 445 in deenergizing opens 110

120

125

130

the loop circuit to the incoming selector switch at armatures 446, 451, and 457. At armature 447 and its working contact it removes ground from the release trunk conductor 26 and from the holding conductor 6 to open the circuits of relays 400 and 419 in case these relays have again operated after ground was disconnected from conductor 20. All the relays in the repeater switch R1 have 5 now been restored to normal and the loop circuit to the incoming selector IS1 has been opened so that line relay 500 and release relay 502 release, these relays having been energized when the incoming selector was seized by the repeater. All of the equipment used in the establishment of a connection has now been restored to normal and is 10 available for further calls.

15 20 *Call from manual exchange to substation T2 in exchange B*

It will now be assumed that the operator at the manual exchange receives a request for a connection to the subscriber at substation 25 T2 in automatic exchange B. Since the manual exchange B can be reached only by way of exchange A, the operator inserts the plug P of cord circuit CC into jack J, thereby seizing the trunkline extending to automatic exchange A and causing the trunk circuit TC to transmit a preliminary impulse of alternating current over the trunk line to repeater R1. Repeater R1 responds to this impulse and closes a loop circuit extending to the incoming selector IS1 in the manner previously 30 described. The operator then proceeds to dial digit 9 followed by the telephone of the subscriber at substation T2 which in this case is 332. Trunk circuit TC responds to the 35 dialling operation and transmits impulses of alternating current over the trunk line in accordance with the dialled digit. Repeater R1 repeats these impulses by interrupting the circuit to incoming selector IS1 in the same 40 manner as described for a call from the manual exchange to automatic exchange A. However, in this case the first digit is 9 and the wipers of selector IS1 are, therefore, raised to a point opposite the ninth level of the bank. 45 The selector then rotates over this level in search of an idle trunk in the well known manner.

It will be assumed that the trunk accessible 50 over bank contacts 558, 559, and 560 is the first idle trunk and is seized by selector IS1. Responsive to the operation of the switching relay 510, the incoming talking conductors from repeater R1 are switched through and the loop circuit is extended over conductors 55 50 and 31 to the repeater R2. Repeater R2 is shown only in skeleton form but is in all respects similar to the repeater R1 shown in Fig. 4 of the drawing. When the repeater R2 is seized by the incoming selector IS1 it 60 transmits a preliminary seizing pulse over

the trunk line comprising conductors 658 and 659 extending to the automatic exchange B. The preliminary impulse is received by the repeater R3 which is in all respects, the same as repeaters R1 and R2 and prepares 70 this repeater and the incoming selector IS3 in exchange B for operation. Responsive to the dialling of the subscriber's digits, repeater R1 opens the loop circuit to repeater R2 responsive to the receipt of alternating current impulses over the trunk line from the manual exchange and repeater R2 converts 75 these impulses into alternating current impulses which are transmitted over the trunk line to exchange B. The repeater R2 in this connection operates in the same manner as repeater R1 on a connection from substation T1 in automatic exchange A to the manual exchange. The operation of repeater R3 is 80 the same as described for repeater R1 in the establishment of a connection from the manual exchange to the automatic exchange A. Thus the incoming selector IS3 is raised to the third level responsive to the first of the subscriber's digits and automatically searches 85 for an idle connector. Assuming that the connector C3 is the first one available, this connector is seized and responds to the last two digits 3 and 2 to connect with the line of substation T2.

When the subscriber at substation T2 answers, connector C3 reverses the battery connections over the trunk line to repeater R3. Repeater R3 transmits an alternating current impulse for answering supervision over trunk line conductors 658 and 659 to repeater R2 in exchange A. Responsive to this alternating current impulse repeater R2 reverses the battery connections to repeater R1 which in turn transmits an alternating current impulse for 90 answering supervision over trunk line conductors 1 and 2 to the manual exchange. This alternating current impulse is received by the trunk circuit TC and extinguishes the supervisory lamp 215 at the operator's position.

At the end of the conversation when the called subscriber T2 replaces his receiver, repeater R3 transmits an alternating current disconnect signal over trunk line conductors 658 and 659 in the manner previously described for repeater R1 in a connection from the manual exchange to automatic exchange A. Repeater R2 responds to this alternating current impulse and again reverses the battery connection to normal over the trunk line from repeater R1. Repeater R1 thereupon transmits an alternating current disconnect signal over trunk line conductors 1 and 2 to the manual exchange, which causes 100 the trunk circuit TC to again light the supervisory lamp 215 to indicate to the operator that the called subscriber has hung up his receiver. The manual operator now removes the plug P from jack J thereby causing 105 110 115 120 125 130

trunk circuit TC to transmit a long alternating current impulse over the trunk line to release the connection. Repeater R1 responds to this impulse and opens the loop circuit extending to repeater R2. Repeater R2 transmits a long alternating current release signal over trunk line conductors 658 and 659 when its incoming loop circuit is opened. The signal is received by repeater R3 in automatic exchange B which in turn opens the loop circuit to the incoming selector IS3 and connector C2, thereby causing these switches to return to normal. All of the automatic equipment used in the establishment of a connection has now been returned to normal.

Calls from substation T2 in exchange B to substation T3 in exchange A

Subscribers in exchange B may call subscribers in exchange A and vice versa without the aid of the operator. Assuming that the subscriber at substation T2 in exchange B wishes to call the subscriber at substation T3 in exchange A, he lifts his receiver thereby causing the lineswitch LS2 to search for an idle trunk extending to a first selector. Assuming that the trunk extending to selector S2 is connected with, the calling subscriber dials the digit 0 thereby operating the selector to connect with a trunk extending to an idle repeater, such as repeater R3. The calling subscriber then proceeds to dial the digits in the telephone number of the desired subscriber, which in this case are 323. Responsive to the seizure of repeater R3, an alternating current impulse is transmitted over trunk line conductors 658 and 659 to the repeater R2 in automatic exchange A to prepare this repeater and incoming selector IS2 for operation. This alternating current impulse is received by repeater R2 in exchange A and this repeater closes the loop circuit extending to the incoming selector IS2. Repeater R3 responds to the impulses of the dialled digits 323 and repeats corresponding alternating current impulses over the trunk line to exchange A. These impulses are received by repeater R2 and converted into direct current impulses to operate the incoming selector IS2 and connector C1 to extend the connection to the line of substation T3. When the subscriber at substation T3 lifts his receiver to answer the call, connector C1 reverses battery over the incoming line by causing repeater R2 to transmit an alternating current impulse over the trunk line to exchange B to indicate that the called subscriber has answered. This impulse is received by repeater R3 and it in turn reverses the battery over the calling loop to operate a meter in case metered service is used. The connection from substation T2 to T3 has now been completed and the conversation may take place.

65 The operation of repeater R3 in the estab-

lishment of the above connection is the same as the operation of repeater R1 in the establishment of a connection from substation T1 in exchange A to the manual exchange. The operation of repeater R2 is the same as the 70 operation of repeater R1 in the establishment of a connection from the manual exchange to substation T3 in the automatic exchange A. The operation of these repeaters was fully described in connection with the establishment 75 of these telephone connections and it is, therefore, not thought necessary to repeat this operation at this time.

At the end of the conversation, assuming that the calling subscriber at substation T2 80 is the first to replace his receiver, the loop circuit extending to repeater R3 in exchange B is broken and the repeater R3 transmits a release signal over the trunk line conductors 658 and 659. Repeater R2 in exchange A 85 responds to this release signal and opens the loop circuit extending to the incoming selector IS2 and the connector C1, thereby causing the switches to release. Repeaters R2 and R3 then restore to normal and repeater 90 R3 removes ground from the release trunk conductor in exchange B, thereby permitting the selector S2 and lineswitch LS2 to restore to normal. All of the equipment used in the establishment of the connection has 95 now been returned to its normal position and is available for further calls.

Assuming that the called subscriber at substation T3 is first to replace his receiver, connector C1 reverses the battery connections 100 to the incoming line extending to repeater R2, thereby causing repeater R2 to transmit an alternating current impulse over the trunk line conductors 658 and 659 extending to exchange B.

This alternating current impulse is received at repeater R3 and operates the impulse responding relay, such as relay 435 of repeater R1, shown in Fig. 4 of the drawings, thereby causing the operation of the impulse correcting relays in repeater R3 which are similar to relays 488, 494, and 499 of repeater R1. The relays, such as 494 and 499, are locked energized to a conductor corresponding to conductor 11 as long as the alternating current impulse is being received. At an armature similar to armature 441 of relay 499, ground is connected through the back contact of an armature similar to 453 and said armature, back contacts of an armature similar to 479 and said armature, armature similar to 465 and its working contact, conductor such as 19, an armature similar to 429 and its working contact, to the lower terminal of the winding of a relay, such as 400. The relay in repeater R3 corresponding to relay 400 in repeater R1 releases and at an armature similar to armature 402 it connects ground to conductor corresponding to conductor 17, thereby causing the operation 125 130

of a relay corresponding to relay 458. This relay opens the circuit of the battery reversing relay corresponding to relay 461 and maintains this relay operated as long as the ground is connected to the conductor corresponding to conductor 17. At the end of the alternating current impulse, the impulse correcting relays corresponding to relays 494 and 499 release and remove ground from the relays, such as 458 and 461. The relay, such as 458, is slow-to-release and, therefore, maintains the locking circuit of relay, such as 461, opened until this relay has been released. The latter relay in releasing reverses the battery connections back to normal. After an interval the relay, such as 458, releases without further effect.

When the calling subscriber at substation T2 replaces his receiver, the loop circuit extending through selector S1 to repeater R3 is opened and the relay, such as 466, of repeater R1 releases, opening the circuit of the release relays, such as 468 and 426. These relays release and bring about the sending of the alternating current release impulse over the trunk line conductors 658 and 659 to automatic exchange A in the manner described in connection with a call from subscriber T3 in automatic exchange A to the manual operator. Repeater R2 responds to this release impulse in the manner previously described and brings about the release of the automatic equipment in exchange A. Repeater R3 in exchange B releases and removes ground from the release trunk conductor, thereby allowing the selector S2 and the line-switch LS2 to release. All the equipment used in the establishment of a connection has now been restored to normal and is available for further use.

Call from substation T2 in exchange B to the manual exchange

In case a subscriber, such as the one at substation T2 in automatic exchange B, wishes to establish a connection which can be completed only by the manual operator, he lifts his receiver and dials the digit 0 to extend a connection to exchange A and then a second digit 0 to extend a connection to the manual exchange. The operation of repeaters R3 and R2, in this case, is the same as just described for a connection from the subscriber at substation T2 to the one at substation T3 in automatic exchange A. In this case the incoming selector IS2 is operated to its tenth level and selects an idle repeater, such as R1, terminating trunks to the manual exchange. The operation of repeater R1 has been fully described in connection with a call from substation T1 in exchange A to the manual exchange. The establishment of the connection and the release of the switches at the end of the conversation, in this case, is in all respects similar to the cases which have been

previously described, and it is not thought necessary to explain this operation in detail.

What is claimed is:

1. The method of extending a connection to a called station and of supervising the connection thereto which comprises the transmission and receiving of alternating current impulses of the same frequency but of different predetermined duration and translating said impulses into corresponding switching movements and supervisory functions. 75

2. The method of extending a connection from a first exchange to a called line in a third exchange by way of a second exchange which comprises the transmission and receiving of alternating current impulses of the same frequency but of different durations at the terminating exchanges and translating said impulses into corresponding switching movements and supervisory functions, and repeating said impulses at the second exchange by translating them first into corresponding direct current impulses and then again converting them into alternating current impulses of said different durations for transmission to the terminating exchanges. 80

3. In a telephone system, a first and a second exchange connected by a trunk line, automatic switches, means including said trunk line and said automatic switches for connecting stations of said exchanges, a source of alternating current in each exchange, and means for applying said sources to said trunk line to transmit impulses over the trunk line for controlling the actuation of said switches and for performing the supervisory and release functions, the impulses for performing each function being of a different length than the impulses for performing every other function. 90

4. In a telephone system, two exchanges connected by a trunk line, a source of alternating current in each exchange, automatic switches in each exchange, means including said trunk line and automatic switches for connecting stations of said exchanges, means for connecting the A. C. source in the calling exchange to said trunk line to operate the switches in the called exchange and to release said switches, means for connecting the A. C. source in the called exchange to said trunk line to transmit answering and disconnect signals to the calling exchange, said connections being made for different predetermined lengths of time depending upon the function to be performed by the signal, and means in each exchange responsive to said signals for performing the proper operations dependent upon the length of the signals. 115

5. In a telephone system, a trunk line accessible at an operator's position and extending to an automatic exchange, a repeater in said trunk line, means in said repeater responsive to the seizure of said trunk line at the operator's position for transmitting an 120 125 130

alternating current seizing signal thereover, means for translating dialling and release signals from the operator's position into alternating current signals and for transmitting the same over said trunk line, means for receiving alternating current answering and disconnect signals over said trunk line and converting the same into corresponding signals at the operator's position, each of the signals transmitted and received over the trunk line comprising alternating current impulses of different duration than the impulses of every other signal.

6. In a telephone system, a trunk line accessible at an operator's position and extending to an automatic exchange, a repeater in said trunk line, means in said repeater responsive to the seizure of said trunk line for transmitting an alternating current impulse of predetermined length thereover to prepare the equipment in the automatic exchange for operation, means for translating direct current dialling impulses into corresponding alternating current impulses for transmission to the automatic exchange, means responsive to the receipt of alternating current signals over the trunk line for converting the same into answering and disconnect signals at said operator's position, and means responsive to the release of the trunk at the operator's position for transmitting an alternating current impulse of a different predetermined length over the trunk line to release the equipment in the automatic exchange.

7. In a telephone system, a trunk line incoming to an exchange and terminating in a repeater therein, automatic switches in said exchange having access to said repeater, means responsive to the seizure of said repeater by one of said switches for transmitting an alternating current calling impulse over said trunk line, means responsive to dialling impulses for transmitting alternating current dialling impulses over said trunk line, means responsive to the receipt of an alternating current answering signal over said trunk line for reversing the battery connections to said switch, and means responsive to the release of the repeater by said switch for transmitting an alternating current release signal over said trunk line.

8. In a telephone system, a trunk line incoming to an automatic exchange and terminating in a repeater, an automatic switch connected to said repeater, means in said repeater responsive to the receipt of an alternating current impulse of a predetermined duration for preparing said switch for operation, means responsive to alternating current impulses of different duration for translating the same into direct current impulses to operate said switch, means responsive to the reversal of the connections to said switch for transmitting an alternating current an-

swering signal of predetermined length over said trunk line, means for transmitting an alternating current disconnect signal of a different predetermined length over said trunk line when the connections to said switch are again reversed to normal, and means responsive to the receipt of an alternating current release impulse of greater length than any of said other impulses over said trunk line for opening the connections to said automatic switch to release the same.

9. In a telephone system, a manual and an automatic exchange connected by a trunk line, automatic switches in said automatic exchange, means responsive to the seizure of said trunk line at the manual exchange for transmitting a seizing impulse of A. C. of predetermined length thereover to prepare the switches in the automatic exchange for operation, means for transmitting A. C. impulses over said trunk line to operate said automatic switches to extend a connection to the desired called line, means responsive to the answering of the called subscriber for transmitting an A. C. impulse of a second predetermined length to the manual exchange for an answering signal, means responsive to the disconnection of the called subscriber for transmitting an A. C. disconnect signal of a third predetermined length to the manual exchange, and means responsive to the freeing of the trunk line at the manual exchange for transmitting an A. C. impulse of a fourth predetermined length over the trunk line to release the switches in the automatic exchange.

10. In a telephone system, a manual and an automatic exchange connected by a trunk line terminating in a repeater in each exchange, automatic switches operable by a calling subscriber in the automatic exchange to extend his line to the repeater in that exchange, means responsive to the seizure of said repeater for transmitting an impulse of alternating current over said trunk line, means in the repeater in the manual exchange responsive to said impulse for signalling the operator, means responsive to the answering of the call by the operator for transmitting an alternating current impulse to said automatic exchange for answering supervision, means responsive to the disconnection of the calling subscriber for transmitting an alternating current impulse to the manual exchange and for restoring the equipment in the automatic exchange to normal, means in the repeater in the manual exchange responsive to said impulse for operating a disconnect signal and for transmitting an alternating current impulse to the automatic exchange to prepare the equipment therein for operation, and means responsive to the freeing of said trunk line by the operator for transmitting an alternating cur-

- rent impulse to the automatic exchange to release said equipment.
11. In a telephone system, a manual exchange and two automatic exchanges, a 5 trunk line connecting the manual exchange and the first automatic exchange, a second trunk line connecting the first and second automatic exchanges, means at the manual exchange for transmitting alternating current impulses over said first trunk line, automatic switches in said first automatic exchange, means for translating said alternating current impulses into direct current impulse to operate said switches to connect with 10 said second trunk line, means for thereafter translating said alternating current impulses into direct current impulses and for retranslating the direct current impulses into alternating impulses for transmission over said 15 second trunk line, automatic switches in said second automatic exchange, and means translating the alternating current impulses into corresponding direct current impulses to operate said switches in the second automatic exchange into engagement with a desired line. 20
12. In a telephone system comprising both manual and automatic exchanges in which the control of inter-office connections is effected by means of alternating current impulses of different lengths transmitted over the inter-office trunk lines, means in the manual exchange responsive to the seizure of an idle trunk line to one of said automatic exchanges for transmitting a preliminary impulse of alternating current over said trunk line to prepare the switches in the automatic exchange for operation, means responsive to the freeing of the trunk line 25 for transmitting an alternating current impulse over the trunk line to release the switches in the automatic exchange, and means responsive to the receipt of a disconnect signal from the automatic exchange in 30 case a calling subscriber in the automatic exchange replaces his receiver for transmitting an alternating current impulse to said automatic exchange to again seize the switches therein to prevent such seizure by 35 the release impulse which is sent out when the trunk is freed. 40
13. In a telephone system, a manual exchange, a trunk line extending to an automatic exchange, means responsive to the seizure of said trunk line at the manual exchange for transmitting an alternating current impulse to the automatic exchange to 45 prepare the switches in that exchange for operations, means for transmitting alternating current impulses over said trunk line to 50 operate the switches in the automatic exchange into engagement with a desired line, means for signalling the operator in case the called line is busy, a key in said manual exchange, means responsive to a momentary 55
- operation of said key for transmitting an alternating current impulse of a definite length over said trunk line, and means in said automatic exchange responsive only to an impulse of said definite length for establishing a talking connection to the busy called line. 60
14. In a telephone system, a manual and an automatic exchange connected by a trunk line, automatic switches in the automatic exchange, a source of alternating current in each exchange, means including said trunk line, said sources of alternating current and said automatic switches for establishing a connection from said manual exchange to a desired called line in said automatic exchange and for supervising said connection, means for signalling the operator in case the called line is busy when connected with, means controlled by the operator for connecting the source in the manual exchange to said trunk line to transmit an alternating current impulse of predetermined duration to the automatic exchange, and means in the automatic exchange responsive to said impulse for causing said switches to establish a talking connection with the busy called line. 70
15. In a telephone system, a manual and an automatic exchange connected by a trunk line, an operator's position having access to 75 said trunk line in the manual exchange, a connector switch in the automatic exchange, means including said trunk line and said switch for extending a connection from said operator's position to a called line in the automatic exchange, means for signalling the operator at said position in case said line is busy, a key at said position, means responsive to a momentary operation of said key for transmitting an alternating current impulse of predetermined duration over said trunk line, means in the automatic exchange responsive to said impulse provided it is of said predetermined duration for grounding the two line conductors extending to said 80 connector switch, and means in said switch responsive to said last means for establishing a talking connection with the busy called line. 85
16. In a telephone system, a connector switch, means for operating said switch to connect with a called line, means for signalling said line if the same is idle, a ring-cut-off relay operated responsive to the answering of the called subscriber, a busy relay operated in case said line is busy when connected with, and means controlled by said busy relay for operating said ring-cut-off relay. 90
17. In a telephone system, a connector switch, means for operating said switch to connect with a called line, means for testing the busy or idle condition of said line, a ring-cut-off relay, and means for operating said relay at the end of the test period in case 95 100

said line is busy and responsive to the answering of the called subscriber in case said line is idle.

18. In a telephone system, a connector switch, means for operating said switch over its incoming line to connect with a called line, a ring-cut-off relay in said switch, means for operating said ring-cut-off relay in case said called line is busy when connected with, a switching relay, means controlled over said incoming line for operating said switching relay to establish a talking connection to the busy line, and means controlled over said incoming line for releasing said ring-cut-off relay to signal the called line after the same has become idle.

19. In a telephone system, a connector having a test relay and a ring cut-off relay, means controlled over the incoming line conductors for operating said switch into engagement with the bank contacts associated with a called line, means responsive to the encountering of a busy potential on the test bank contact for operating said test and ring cut-off relays, and means responsive to the placing of ground potential on said incoming line conductors for completing a talking connection to the busy line and for locking said test relay energized dependent upon the busy potential on said test bank contact.

20. In a telephone system, a connector having a ring-cut-off relay, a test relay, and a switching relay, means controlled over incoming line conductors for operating said switch into engagement with the bank contacts associated with a called line, means responsive to the encountering of a busy potential on the test bank contact for operating said test and ring cut-off relays, means controlled by said test relay for removing all battery connections to the line wipers of said switch, and means responsive to the placing of ground potential on said incoming line conductors for operating said switching relay to complete a talking connection to the busy line.

21. In combination, a signal receiver, an incoming circuit over which three different lengths of impulses are received, three control circuits, a group of relays in said receiver responsive to received impulses, a second group of relays selectively controlled by said first group dependent upon the length of the received impulse, and means controlled by said two groups of relays for exercising control functions over the proper one of said control circuits as designated by the length of the received impulse.

22. In combination, a signal receiver, an incoming signalling circuit over which impulses of three different lengths are received, an outgoing control circuit, a group of relays in said receiver selectively responsive to said impulses, means controlled by said relays for performing three different control

functions over said control circuit dependent upon the length of received impulses, and means in said receiver controlled over said control circuit for transmitting impulses of two different lengths over said incoming signalling circuit.

In witness whereof, I hereunto subscribe my name this 26th day of May, A. D. 1931.

JOHN WICKS.
